UNITED STATES PATENT OFFICE.

WINFRED T. POWELL, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

1,356,010.

Specification of Letters Patent. Patented Oct. 19, 1920.

Application filed April 14, 1917. Serial No. 161,956.

To all whom it may concern:

Be it known that I, WINFRED T. POWELL, a citizen of the United States of America, and resident of Chicago, Cook county, Illinois, have invented certain new and useful Improvements in Automatic Telephone Systems, of which the following is a specification.

My invention relates in general to automatic telephone systems, but is particularly applicable to highly organized systems involving numerous exchanges interconnected by toll lines, the long distance connections being established preferably through the medium of automatic switches; and the object of the invention is to provide new and improved circuits for automatic private branch exchanges included in a system of the above general character, with a view to providing talking circuits of maximum efficiency, and introducing numerous new and advantageous operating features which add appreciably to the quality of the service.

All the different phases of my invention, and the preferred method of constructing and using the same, will be fully described hereinafter, reference being had to the accompanying drawings, comprising Figures 1 to 6, inclusive, which show in diagrammatic form the essential circuits of a system embodying the principles of my invention.

For a clear understanding of the drawings they should be placed in order with the lines at the ends thereof in alinement, and when thus arranged there is shown a complete circuit connection extending from the toll line 2-3 in Fig. 1 to the automatic private branch exchange substation A in Fig. 4. The connection has been established through the medium of the toll operator's cord circuit O, Fig. 1; the toll first selector V, Fig. 2; the toll second selector W; the combination toll and local repeater F, Fig. 3; the two way trunk line comprising conductors 233, 234 and 235, connecting the main exchange with the private branch exchange, and extending through the attendant operator's key circuit M, Fig. 4; the special incoming selector E, Fig. 5; and the special toll connector H, Fig. 6.

The selector and connector switches in the system are preferably of the well known Strowger vertical and rotary type, the mechanical construction of which is disclosed in the U. S. patents to Keith, Erickson, and

Erickson, Nos. 815,321, and 815,176, both granted March 13, 1906. In the selector switches, however the side switches and private magnets have been omitted and all circuits, including the connector circuits, 60 have been revised in accordance with modern two-wire practice. There are of course other modifications having to do more particularly with the various features of the invention, all of which will be described in 65 detail hereinafter.

The apparatus shown in Figs. 1 and 2 forms no part of my invention and is shown only to facilitate the understanding of its operation. In Fig. 1, the reference characters 2 and 3 indicate a toll line of some kind which may extend to a distant point. It terminates at the toll switch board in a jack J, and in the usual multiple jacks (not shown). The associated equipment shown 70 in the drawing, comprising the drop 5 and cut-off relay 4, is of the simplest type, and may be replaced or supplemented by any well known apparatus as desired.

The cord circuit O may likewise be of any 80 suitable type, although the calling end must be arranged to coöperate with the toll service trunks. A single supervisory bridge comprising the lower winding of the ringing up and locking relay 8, the condenser 12, 85 and the impedance coil 7, is connected across the two strands of the cord circuit and controls the supervisory lamp L'. The lamp L is the answering supervisory lamp and is controlled by the marginal sleeve relay 9, 90 while the lamp L' is a special supervisory signal controlled by the same relay and whose function it is to inform the operator when a busy line has become idle, all of which will be explained fully hereinafter. 95 Keys K⁴ and K⁵ are the regular ringing keys. The double throw key K' is a combined listening and monitoring key. When thrown in one direction the operator's head set is bridged across the two strands of the cord circuit in the regular manner, but when thrown in the opposite direction the relay 13 is operated, whereby the receiver in series with the resistance 14 is connected across the cord circuit for monitoring purposes. 100 The double throw key K is provided to enable the operator to open the cord circuit conductors on either side of her listening key, whereby she is able to cut-off the subscriber at either end while talking to the 110

subscriber at the other end. The function of key K^2 is to shift the control of the relay 9 from lamp L to lamp L' . The key K^3 is a calling device key through the medium 5 of which the operator may insert the calling device S in the sleeve conductor of the cord. The calling device S may be common to a number of cord circuits, and is of the well known two wire type, such as is dis- 10 closed in the British patent to Dicker, No. 29654 of 1910.

For the purpose of completing toll connections to local subscribers' lines, each toll operator has before her multiple jacks of a 15 group of so-called toll service trunks each of which extends to a toll first selector. A complete toll trunking system involving toll service trunks of the character shown in this application is disclosed in the prior ap- 20 plication of John Wicks, Serial Number 124,358, Patent No. 1,315,444, September 9, 1919, and accordingly this portion of the equipment need not be described in detail. It will suffice to say, referring to the draw- 25 ings, that the operator who has the cord circuit O, has in front of her a plurality of multiple jacks, one of which is the jack J' , from which trunk lines extend to toll first selectors, one of which is the selector V. 30 The toll first selectors have access to trunk lines terminating in toll second selectors, such as the selector W; and the toll second selectors in turn have access to trunk lines which terminate in connectors having ac- 35 cess to the local subscribers' lines in the main exchange. These connector switches are not shown, but it may be mentioned are acces- 40 sible also from the second selectors of the regular main exchange trunking system. If desired the toll second selectors may also be accessible to incoming toll selector repeaters of the type shown in the previously mentioned application of Wicks, and a multiple which may extend to the bank of one 45 of these selector repeaters is shown at the top of Fig. 2; but since my invention is not limited to use in connection with any particular trunking system it has been thought unnecessary to show all these details.

Having explained briefly the general layout of the main exchange, attention will now be directed to the equipment of the branch exchange. The automatic private branch exchange partially shown in Figs. 4, 55 5 and 6, is a three digit system, that is, local connections are established through the medium of first selectors and connectors, and ordinarily the capacity would be 1000 lines. Since the tenth level of the selectors however 60 is reserved for calling the main exchange, the actual capacity is 900 lines. The branch exchange then may be considered as being fundamentally a standard automatic exchange provided with first selectors and con- 65 nectors. As is customary, the subscribers'

lines are given access to the selector switches through the medium of individual line or trunk selecting switches which will be more particularly referred to later. In addition to the local trunking system briefly de- 70 scribed above, the branch exchange is connected with the main exchange by trunk lines; and is also provided with an attendant operator's switchboard. Each trunk line connecting the main exchange with the 75 branch exchange goes through a key circuit at this switchboard, whereby the attendant operator is enabled to exercise a control over the connections established thereover; and it is this control, which may be only of 80 a supervisory nature, or which may consist of actual participation in the establishment of connections, which forms some of the principal subject matter of the invention. In addition to the trunk line key circuits, 85 the attendant's switchboard is provided with a few other key circuits which are for the purpose of giving special service to import- than subscribers at the branch exchange. For example, assuming that the branch exchange 90 is installed in a large manufacturing es- tablishment, the important officials of the company will usually demand a special serv- ice, which on account of the expense it would be impracticable to give to the great ma- 95 jority of the telephone users. The lines from the telephones of these officials there- fore are extended through special key cir- 100 cuits at the attendant's switchboard before they terminate in their individual line switches.

This may be more readily understood by a consideration of the line of substation A, Fig. 4, which is assumed to be a special service line. The telephone instrument it- 105 self may be of any approved common bat- tery type, and as shown herein comprises the receiver 602, transmitter 603, switch- hook 604, ringer 605, and condenser 606. Being an automatic substation there is also 110 provided a calling device, represented here- in by the impulse springs 607 and 608 and the impulse wheel 609, which may be of the type disclosed in the British patent to Dicker previously referred to. 115

The line conductors 612 and 613 extend to the attendant's switchboard, where they pass through contacts in the key circuit equipment N before continuing by way of conductors 650 and 653 to the individual 120 line switch C, Fig. 5. The key circuit N comprises a group of relays whose func- tions will be described later, the line and supervisory lamps L' and L^8 , and three keys. Of these latter, the key K^{11} is a ringing 125 key; the double throw key K^{12} is a combined listening and calling device key; while the key K^{13} is a combined release and restricted service key.

The individual line switch C and the mas- 130

- ter switch D, Fig. 5, are of the type disclosed in U. S. Letters Patent No. 1,078,690, granted Jan. 17, 1912, to Frank Newforth, reissued April 13, 1915, No. 13,901. Line 5 and master switches of the foregoing type are well known and need no detailed description. It will be sufficient to say that through the medium of line switch C the line of substation A is given access to a 10 plurality of selector switches one of which is the selector E'. The master switch D, it will be understood, serves to control the line switch C and other similar line switches in the selection of idle selector switches.
- 15 The selector E' and the connector H', as before mentioned, are of the well known Strowger vertical and rotary type and need no description other than that which will be given in the description of the operation 20 of the system.
- Both the main and branch exchanges having been briefly described we will now consider the means by which the two are interconnected. In the description of the trunking in the main exchange it was explained 25 that the toll second selectors such as the selector W, Fig. 2, had access to groups of connector switches which in turn had access to subscribers' lines, these connectors being 30 also accessible to second selectors of the regular main exchange trunking system. Where there are private exchanges subsidiary to the main exchange, however, as in the present case, a certain selector level 35 must be reserved for calling the branch exchanges, and in order to not reduce the capacity of the main exchange more than necessary these branch exchange trunks are preferably taken off from the banks of the 40 last selectors before the connectors, which in this case are the second selectors. Thus all of the levels of the toll second selector W do not contain terminals of trunk lines extending to the connector switches, but a 45 certain level as for example the tenth level, is set apart for the branch exchange trunks. Of course the corresponding level in the regular second selectors will also be reserved for the same purpose.
- 50 In Figs. 3, 4, and 5, one of the interconnecting trunk lines and its accessories is shown complete, the trunk line proper being indicated by the reference characters 233, 234, and 235. At the main exchange 55 it has two branches, one of which terminates in the repeater F, and the other in the line switch C'. The repeater F comprises a group of relays whose functions will be described later; and is accessible to the toll 60 second selectors such as the selector W, Fig. 2, and also to the second selectors of the regular main exchange trunking system, thus forming the means by which selectors of both kinds are given access to the associated trunk line. In the case of the selec-
- tor W and similar toll second selectors, connection may be extended to the repeater F and thence to the trunk line under consideration by way of the trunk conductors 160-164, inclusive; but in the case of the 70 selectors of the regular exchange trunking system, access thereto is had by way of the trunk conductors 165-167, inclusive. In the system illustrated the trunks leading from the second selectors extend directly to 75 the repeater F, there being but a single group of branch exchange trunk lines. In case there are a plurality of branch exchanges, however, it will be understood that third selectors may be interposed in order 80 to handle the plurality of groups of trunk lines which would then be necessary.
- The line switch C' affords means whereby connections from the branch exchange may be extended to subscribers in the main exchange by way of the regular main exchange trunking system. The line switch C' is similar to the line switch C, Fig. 5, already described, and has access to selector switches over a group of trunk lines, one of which, 85 comprising the connectors 241, 242, and 243, is partially shown to the left of the line switch.
- At the branch exchange the conductors 233, 234, and 235 of the interconnecting 90 trunk line extend by way of contacts in the key circuit equipment M, Fig. 4, to the conductors 380, 382, and 389, respectively, which terminate in the incoming selector E, Fig. 5; there being also a branch comprising 95 the conductors 750, 386, and 751, which extends to multiple contact sets in the tenth level of the local first selectors such as the selector E'. The key circuit equipment M comprises the group of relays 300 to 304, inclusive; four lamp signals, comprising the busy lamp L¹, the line lamp L², the guard lamp L³, and the supervisory lamp L⁴; and five keys, of which the key K⁶ is a combined 100 release and calling device out key, key K⁷ is a special key which I term a "hold" key, key K⁸ is a combined listening and calling device in key, key K⁹ is a special key which will be referred to hereafter as a "call 105 through" key, and key K¹⁰ is a release in key. The explanation of the functions of these relays, lamps, and keys can best be made by describing the operation of the 110 system and will therefore be deferred until later.
- The incoming selector E is in general 115 similar to the other selector switches of the system, that is, it is operable to select a group of trunks and an idle trunk in the selected group; but the circuits are largely 120 revised to accomplish certain features of the invention, and particularly in view of the contemplated inter-dependency between the selector switch and the key circuit equipment M. At this time mention should be 125 130

made of the three sets of shaft controlled springs shown in the drawing just below the relays of the switch. The springs 460, 461, and 462 may be termed "tenth level off normal springs"; in other words, when the shaft arrives at the tenth level spring 461 is shifted from engagement with spring 460 into engagement with spring 462. The springs 463 to 468, inclusive, are the regular 10 off normal springs and are closed together in pairs upon the first upward movement of the switch shaft. The springs 470 to 473, inclusive, are "rotary off normal springs," and are actuated upon the eleventh rotary 15 step of the shaft by any suitable cam arrangement.

The banks of the incoming selectors such as the selector E are not multiplied with the banks of the local selectors such as the 20 selector E', but contain terminals of separate groups of trunk lines which extend to special connectors such as the connector H, Fig. 6. Owing to the absence of ringing equipment and the usual battery supply 25 bridges the circuit of the connector H is very simple. The banks of the special toll connectors are multiplied straight with the banks of the local connectors. In other words, each group of lines in the branch 30 exchange is accessible through a certain number of connectors such as the connector H, and also through a certain number of connectors such as the connector H', the banks of all the connectors being multiplied as 35 shown, in the case of the connectors mentioned, at the right hand end of Fig. 6.

At the top of Fig. 4 and just above the key circuit equipment M there is shown the attendant operator's head set, indicated by 40 the reference character Opr. The only feature of this equipment which needs special mention is the relay 370 which is provided to shift from single wire to loop calling. To explain this a little more fully, the calling 45 device S' is adapted upon the operation of key K^s to be included in a ground return control circuit of the selector E; while when the key K^s is actuated a bridge is closed across the trunk conductors which includes 50 the calling device, the relay 370 being energized to produce the necessary circuit changes. It will be clear of course that the operator's equipment Opr is common to a plurality of key circuit equipments such as 55 the equipment M, and to a plurality of key circuit equipments such as the equipment N.

For the purpose of supplying current for operating and talking purposes I have shown throughout the drawings a plurality of batteries, but it is to be understood that there 60 is preferably but one battery for each exchange, each battery having its positive pole grounded. In order not to encumber the drawings reference characters have been 65 omitted from the separate batteries therein

shown, and to avoid any confusion on this account it is noted that when in the specification a circuit is traced "to battery," it extends to the ungrounded or live pole of the common exchange battery. The reference 70 characters IR, IR', and IR² indicate intermittent ringing machines of which there is preferably one in each exchange. Similarly, each exchange is provided with a busy 75 signaling machine of the usual type which are shown at several places in the drawings and indicated by the reference characters Q, Q¹, etc.

Having described briefly the general layout 80 of the system and the character of the apparatus involved, I will now proceed to explain in a more detailed manner the operation of the circuits. For this purpose it will be assumed that the toll operator having the cord circuit O, Fig. 1, desires to connect the toll line 2-3 with the line of the 85 private branch exchange substation A, Fig. 4, this being the complete circuit connection shown in the drawings. Afterward a number of other connections will be briefly described 90 in order to completely illustrate the different features of the invention.

To proceed with the establishment of the connection, the toll operator, after first observing that the toll service trunk with 95 which the lamp L² is associated is idle, as indicated by the unlighted condition of the said lamp, will insert the calling plug of the cord circuit O in the jack J' of the service trunk. By the insertion of the plug in the jack a control circuit is completed for the line relay 50 of the toll first selector V, Fig. 2, over the following path: ground at G², winding of supervisory relay 9, contacts of the calling device K³, sleeve of the plug, sleeve of jack J', contact spring 15, conductor 16, armature 81 and its resting contact, and the winding of the line relay 50 to battery. Upon the closure of the above 100 circuit relays 9 and 50 are energized in series, the former relay closing a circuit for the supervisory lamp L in an obvious manner. Relay 50, upon energizing, closes a circuit for the slow acting release relay 51 105 which relay upon energizing in turn prepares a circuit for the vertical magnet 57 in the usual manner, and also closes a circuit for the busy lamp L² and its multiples at other operators' positions over the following path: ground at G³, armature 82 and 110 its working contact, conductor 17, and the busy lamp L² to battery. By the illumination of the busy lamps the other operators are warned that the service trunk has been 115 taken for use.

The foregoing operations have occurred in response to the insertion of the plug in the jack. The operator may now proceed to dial the number of the desired subscriber in the private branch exchange, but before 120

so doing she is required first to operate the calling device key K^6 , the actuation of which key results in the substitution of the calling device S for the supervisory relay 9 in the 5 circuit of the line relay 50 of the selector V . When now the calling device is actuated in accordance with the first digit of the required number, a series of interruptions is produced in the circuit of the line relay 50 .

10 Responsive to these interruptions of its circuit, the line relay is deenergized a corresponding number of times and at each deenergization sends an impulse to the vertical magnet 57 over the following path: ground at G^4 , armature 83 and its resting contact, resting contact of armature 84 and the said armature, winding of low resistance relay 52 , armature 85 and its working contact, and the winding of the vertical magnet 57 to battery. In response to these impulses the vertical magnet is actuated to raise the switch shaft step-by-step until the wipers 15 69 to 63 , inclusive, arrive at the horizontal level of bank contacts in which are terminated trunk lines extending to the required group of toll second selectors. The relay 52 is energized in series with the vertical magnet and being slow acting retains its armature attracted during the series of impulses.

20 By the energization of relay 52 an initial energizing circuit is completed for relay 53 as follows: grounded conductor 17 , armature 86 , spring 87 , winding of relay 53 , and the interrupter contact of the rotary magnet 56 to battery. At the first upward movement of the shaft the off-normal springs 58 are permitted to close, whereby the relay 53 , upon energizing, is enabled to complete a locking circuit for itself as follows: grounded conductor 17 , working contact of armature 88 and the said armature, off-normal springs 58 , winding of relay 53 , and the interrupter contact of the rotary magnet 56 to battery. As a further result of the energization of relay 53 a circuit is prepared for the rotary magnet 56 which, however, is held open during the vertical movement of the switch by the slow acting relay 52 . At this point it should be mentioned that as soon as the off-normal springs 58 are closed, the line switching relay 54 is connected in series with the relay 53 over the following path: grounded conductor 17 , winding of the relay 54 , off-normal springs 58 , winding of relay 53 , and the interrupter contact of the rotary magnet 56 to battery. It is to be noted, however, that the above circuit has already been grounded at a point midway between the two relays; whence it follows that the relay 54 is short circuited and remains inoperative for the present.

25 At the end of the series of impulses the slow acting relay 52 deenergizes and completes the circuit of the rotary magnet 56 as follows: grounded conductor 17 , working contact of armature 88 and the said armature, off-normal springs 58 , spring 87 and the contact normally engaged thereby, winding of rotary magnet 56 , and interrupter contacts of the said magnet to battery. The 30 rotary magnet is energized over the above circuit and rotates the switch shaft one step, thereby bringing the wipers 60 to 63 , inclusive, into engagement with the first set of contacts in the level opposite which they were raised. Near the end of its stroke the rotary magnet separates its interrupter contact, thereby breaking its own energizing circuit and also the locking circuit of relay 53 . Relay 53 and the rotary magnet 35 are therefore deenergized, the former opening the circuit of the rotary magnet at a new point, and the rotary magnet again closing its interrupter contact. The operation now depends upon whether or not the first trunk line is busy. If this trunk line is busy, the test contact with which the test wiper 61 is in engagement will have a ground potential upon it, and a circuit will be established by way of the test wiper and the armature 89 of relay 54 which is effective to maintain relay 54 short circuited and to again energize the relay 53 . When the first trunk line is busy, then, the relay 53 will again attract its armature to again close 40 the circuit of the rotary magnet 56 , resulting in the advance of the switch wipers another step. It will be seen then, that the relay 53 will operate as an impulse sender or a stepping relay to advance the switch wipers step-by-step through the medium of the rotary magnet, as long as the test wiper continues to engage grounded or busy test contacts. As soon as the first ungrounded test contact is reached, assumed to be the test contact 65 , and the rotary magnet 56 deenergizes to close its interrupter contact, the relay 54 will no longer be short circuited, but will instantly energize in series with the relay 53 over the circuit previously traced. Relay 54 45 50 remains inoperative. Upon energizing, relay 54 opens the circuit of the release magnet 55 at its armature 84 ; at its armature 89 shifts the connection from the test wiper 61 from its lower to its upper terminal; and at its upper armature 81 , disconnects the conductor 16 from the line relay 50 and extends it instead to the line relay 100 of toll second selector W as follows: conductor 16 , 55 60 armature 81 and its working contact, wiper 62 , bank contact 66 , armature 123 and its resting contact, and the winding of line relay 100 to battery. By the energization of the line relay 100 , a circuit is closed for the slow acting release relay 101 . The relay 101 upon energizing, prepares the usual circuit for the vertical magnet, and also completes a holding circuit extending back to the selector V over the following path: ground at 65 70

G⁵, working contact of armature 125 and the said armature, conductor 70, bank contact 65, wiper 61, and armature 89 and its working contact to conductor 17, where it joins the previously described circuit of the busy lamps, such as the lamp L², Fig. 1. A branch of the above circuit serves to maintain the switching relay 54 energized over the previously traced circuit, including the relay 53. Although the relays 50 and 51 of the selector V are deenergized immediately following the energization of relay 54, owing to the fact that the latter relay is slow acting, ground G⁵ is not disconnected from conductor 17 until after the holding circuit extending back from ground G⁵ is completed. Ground G⁵ also extends by way of a branch conductor 70' to the test contact 72 and its multiples in the banks of the toll selector repeaters having access to the toll second selector W, where by a ground potential on these test contacts said selector is made busy.

The operator may now proceed to manipulate her calling device in accordance with the second digit of the number, thereby producing a series of interruptions in the circuit of the line relay 100 of the toll second selector W. In response to these interruptions of its circuit the line relay 100 deenergizes a number of times and at each deenergization transmits an impulse from ground G⁶ to the vertical magnet 107 over the following path: ground at G⁶, armature 121 and its resting contact, resting contact of armature 118 and the said armature, armature 126 and its working contact, winding of relay 102, and the winding of the vertical magnet 107 to battery. The vertical magnet 107 is accordingly actuated raising the switch shaft step by step until the wipers 150 to 154, inclusive, arrive at the horizontal level of bank contacts in which are terminated trunk lines extending to the private branch exchange repeaters, such as the repeater F. The relay 102 is energized in series with the vertical magnet, and being slow acting, it retains its armature during the series of impulses. At the first upward movement of the shaft the off-normal springs 108 are permitted to close, thereby completing an initial energizing circuit for the relay 103 as follows: ground at G⁶, working contacts of armature 125, armature 127 and its working contact, off-normal springs 108 and the winding of relay 103 to battery. Upon energizing, the relay 103 closes a locking circuit for itself as follows: grounded conductor 70, right hand interrupter contact of the rotary magnet 105, working contact of armature 129 and the said armature, off-normal springs 108, and the winding of the said relay 103 to battery. As a further result of its energization relay 103 prepares a circuit for the rotary magnet 105 which,

however, is held open during the vertical movement of the switch by the slow acting relay 102. As in the case of the toll first selector, the line switching relay, or the relay 110, and the stepping relay, or the relay 103, of the toll second selector, are connected in series upon the initial upward movement of the switch shaft; and as this circuit in the second selector is slightly different from the one already traced in the first selector, it will be advisable to point out the path traversed: grounded conductor 70, winding of relay 110, left hand interrupter contact of the rotary magnet 105, off-normal springs 108, and the winding of relay 103 to battery. Ground G⁵ being connected to the above circuit at the junction of the two relays, relay 110 is short-circuited and inoperative for the present. At the end of the series of impulses the slow acting relay 102 deenergizes and completes the rotary magnet circuit, which may be traced as follows: ground at G⁵, working contacts of armature 125, armature 127 and its resting contact, working contact of armature 128 and the said armature, and the winding of the rotary magnet 105 to battery. The rotary magnet 105 is energized over the above circuit and rotates the switch shaft one step, thereby advancing the wipers 150 to 154, inclusive, into engagement with the first set of contacts in the level opposite which they were raised. Near the end of its stroke the rotary magnet opens both its interrupter contacts, thereby opening the circuit connecting the relays 110 and 103 and also breaking the locking circuit of the latter relay. Relay 103 therefore is deenergized and breaks the circuit of the rotary magnet which deenergizes in turn and again closes its interrupter contacts. The operation now depends upon whether or not the first trunk line is busy. If there is a ground potential upon the test contact with which the wiper 151 is now in engagement, a circuit will be established which will be effective to maintain the relay 110 short-circuited and to again energize the relay 103. This circuit may be traced as follows: ground on busy test contact, test wiper 151, armature 130 and its resting contact, armature 114 and its resting contact, left hand interrupter contact of the rotary magnet 105, off normal springs 108, and the winding of relay 103 to battery. It follows that if the first trunk line is busy relay 103 will again energize to close the circuit of the rotary magnet 105, resulting in the advance of the switch wipers another step. It will be seen from the foregoing that the operation of the second selector W in selecting an idle trunk line is similar to the previously described operation of the first selector V in like case, the shaft being rotated step by step through the conjoint action of the relay 103 and the ro-

130

tary magnet 105 as long as the test wiper 151 continues to engage grounded or busy test contacts. As soon as the first ungrounded test contact is reached, assumed to be 5 the test contact 156, and the rotary magnet 105 deenergizes to close its interrupter contacts, relay 110 will no longer be short circuited but will at once energize in series with the relay 103 over the circuit previously traced. Owing to the high resistance of relay 110, relay 103 remains inoperative. Upon energizing, relay 110 opens a contact in the circuit of the release magnet 106 at its armature 118 in order to guard against 10 the release of the switch upon deenergization of relays 100 and 101; disconnects the test wiper 151 from its own upper terminal at its armature 114 and connects it instead to the resistance 122; at its armatures 115 15 and 116 connects the repeating coil windings 112 and 113 with the upper and lower windings, respectively, of the relay 109; and at its armature 117 completes a control circuit extending to the repeater F, Fig. 3, over a 20 path which may be traced as follows: ground at G^e , armature 121 and its working contact, working contact of armature 117 and the said armature, resistance 170, wiper 153, bank contact 158, conductor 163, upper 25 contacts of the back bridge or reversing relay 200, and the upper winding of the line relay 201 to battery. Line relay 201 is energized upon the closure of the above circuit and completes at its armature 212 a circuit for the slow acting release relay 202. The 30 energization of relay 202 is followed by a number of important results which will be described in detail. First to be considered is the grounding of conductor 166 at the upper armature 213 of the said relay 202, whereby ground G^r is extended by way of the said conductor 166 to the test contact 168 and its multiples in the banks of the local second selectors having access to the 35 repeater F, thus rendering the repeater F busy to these selectors. Ground G^r also extends to the test contact 156 and its multiples in the banks of the other toll second selectors over the following path: ground G^r , working contact of armature 213 and the said armature, conductor 166, winding of the low resistance relay 203, and the conductor 161 to the test contact 156. The relay 203 being of low resistance, test contact 40 45 50 55 60 65 156 and its multiples are brought sufficiently near to ground potential to render the repeater F busy to the toll second selectors also. A continuation of the circuit last traced extends by way of the test wiper 151 of the second selector W, armature 130 and its resting contact, armature 114 and its working contact, and the resistance 122 to battery. Relay 203 is accordingly energized to open a contact in the circuit of relay 205 and with other results which will appear

later. Another result of the grounding of conductor 166 is the energization of the cut-off winding 239 of the line switch C', the energizing circuit of which may be traced as follows: grounded conductor 166, contact 250, spring 251, conductor 237, and the cut-off winding 239 to battery. By the attraction of the cut-off armature 240 the conductors 236 and 238 are disconnected from their normal battery and ground connections in the line switch C'. Still another result of the energization of the relay 202 is the closure of a circuit for the relay 208 over the following path: ground at G^r , working contacts of armature 213, armature 223 and its resting contact, and the winding of relay 208 to battery. The relays 203 and 208 being now energized, it will be seen that the incoming line conductors 160 and 164 are extended by a direct metallic connection 85 through the repeater to the trunk conductors 233 and 235, respectively.

By the energization of relay 208 a control circuit extending to the incoming selector E at the branch exchange is closed as follows: ground at G^s , armature 229 and its working contact, resistance 209, conductor 234, contact springs 328 and 327 of key K^s at the attendant operator's position, Fig. 4, contact springs 315 and 316 of key K^{10} , conductor 382, armature 419 of relay 404 of the selector E, Fig. 5, and its resting contact, and the winding of the line relay 400 to battery. The line relay 400 is energized upon the closure of the above circuit and completes the usual energizing circuit for the slow acting release relay 401. By the energization of the latter relay the circuit of the vertical magnet 411 is prepared in the usual manner, and at the same time ground G^{10} is connected to the conductor 383. A circuit for the busy lamp L^{13} at the attendant operator's position may now be traced as follows: ground G^{10} , working contact of armature 409 and the said armature, conductor 383, contact springs 317 and 318 of key K^{10} , conductor 386' and the busy lamp L^{13} to battery. The illumination of the busy lamp L^{13} indicates to the attendant operator that the trunk line associated therewith has been 90 95 100 105 110 115 120 125 130 taken for use. A branch of the above circuit extends by way of conductor 386 to the test contact 752 and its multiples in the banks of local first selectors, including the selector E', where by ground potential on these test contacts the trunk line under consideration is made busy to outgoing calls from the branch exchange.

To summarize briefly the operations that have taken place so far, the toll operator at 125 the main exchange by dialing the first two digits of the number has operated the toll first selector V and the toll second selector W, to extend the connection by way of the repeater F and the trunk line associated

therewith to the incoming selector E at the branch exchange; and by the operation of the relays 400 and 401 of the incoming selector a busy signal at the attendant's position has been lighted and the trunk line in use has been made busy to the local first selectors at the private branch exchange.

The toll operator may now proceed to dial the digits which are to control the incoming selector E and the connector H, Fig. 6, to complete the required connection. By the operation of the calling device in accordance with the next digit called a series of interruptions is produced in the circuit of the line relay 100 of the selector W as before. The line relay is accordingly de-energized a number of times, and at each de-energization interrupts the circuit of the line relay 201 of the repeater F, Fig. 3. Responsive to these interruptions of its circuit, the line relay 201 is also de-energized a number of times to repeat the interruptions into the circuit of the line relay 400 of the incoming selector E, Fig. 5. It follows that the relay 400 will be de-energized a number of times corresponding to the digit called, and will transmit at each de-energization an impulse to the vertical magnet 411 over the following circuit: ground at G¹¹, armature 408 and its resting contact, resting contact of armature 423 and the said armature, armature 410 and its working contact, winding of relay 402, and the winding of the vertical magnet 411 to battery. In response to these impulses the vertical magnet 411 is actuated to raise the switch shaft step by step until the wipers 440 to 443, inclusive, arrive at the horizontal level of bank contacts which are terminals of trunk lines extending to the required group of toll connector switches. The relay 402 which is included in the vertical magnet circuit is slow acting and retains its armatures attracted during the series of impulses. At the first upward movement of the shaft the off-normal springs 467 and 464 are permitted to close, thereby completing an initial energizing circuit for the stepping relay 403 as follows: grounded conductor 383, armature 414 and its working contact, off-normal springs 467 and 464, winding of relay 403, conductor 387, contact springs 334 and 333 of key K⁸, and contact springs 313 and 312 of the "call through" key K⁹ to battery. (It is to be noted that the "call through" key K⁹ is assumed to be in operated position. The function of this key in blocking calls will be explained fully later on, and it will be sufficient for the present to call attention to the fact that the relay 403 of the selector E is supplied with battery through the contacts of this key.) Upon energizing, relay 403 completes a locking circuit for itself as follows: ground at G¹², working contact of armature 417 and the said armature, interrupter contact of the rotary magnet 412, off-normal springs 467 and 464, winding of the said relay 403, conductor 387, contact springs 334 and 333 of key K⁸ and contact springs 313 and 312 of key K⁹ to battery. At its upper armature 416 relay 403 prepares a circuit for the rotary magnet 412 which is held open during the operation of the vertical magnet by the slow acting relay 402. The usual circuit connecting the switching relay 404 and the stepping relay 403 in series may be traced as follows: grounded conductor 383, rotary off-normal springs 471 and 470, winding of relay 404, interrupter contact of the rotary magnet 412, off-normal springs 467 and 464, winding of relay 403, conductor 387, and thence over the path previously traced to battery by way of the "call through" key K⁹. This circuit being grounded at the junction of the two relays, as previously explained, relay 404 is short-circuited and remains de-energized for the present. At the end of the series of impulses which control the vertical operation of the switch, the slow acting relay 402 retracts its armatures, thereby completing a circuit for the rotary magnet 412 as follows: grounded conductor 383, armature 414 and its resting contact, working contact of armature 416 and the said armature, and the winding of the rotary magnet 412 to battery. Upon closure of its circuit the rotary magnet is energized to advance the wipers 440 to 443, inclusive, into engagement with the first set of contacts in the level opposite which they were raised. Near the end of its stroke the rotary magnet breaks the locking circuit of relay 403 which relay is accordingly de-energized to break the circuit of the rotary magnet, which also de-energizes. The operation of selecting an idle trunk line which now takes place is similar to the corresponding operations already described in the case of toll selectors V and W, and need not be described in detail. It will be sufficient to say that as long as the test wiper 442 of the selector E engages busy or grounded test contacts, the switch shaft will continue to be rotated by the co-operative action of the stepping relay 403 and the rotary magnet 412, the relay 404, meanwhile, being short-circuited and inoperative. When the test wiper 442 arrives at the first ungrounded test contact, assumed to be the test contact 446, and the rotary magnet 412 retracts its armature, the relay 404 will instantly energize in series with the relay 403 over the circuit previously traced, the latter relay remaining inoperative owing to the high resistance of relay 404. Upon energizing, relay 404 opens a contact in the circuit of the release magnet 413 at its armature 423 in order to prevent the release of the switch upon de-energization of relays 400 and 401; shifts test wiper 442 from its own upper terminal 130

to its lower terminal at armature 418; connects the lower terminal of winding of relay 403 to the resistance 450 at its armature 421, for a purpose to be described later; at 5 its armatures 420 and 422 connects up the line wipers 440 and 443; and at its armature 419 disconnects the operating conductor 382 from the line relay 400 and connects it instead to the line relay 500 of the connector H over the following path: conductor 10 382, armature 419 and its working contact, wiper 441, bank contact 445, and the line relay 500 to battery. Following the closure of the above circuit the line relay 500 is energized 15 to close the usual circuit for the slow acting release relay 501. This latter relay, upon energizing, prepares the usual circuit for the vertical and rotary magnets 506 and 507, and also connects the ground G¹⁴ to the conductor 383 as a substitute for ground G¹⁰, 20 which is removed upon the deenergization of relays 400 and 401. This substitute ground connection or holding circuit is established as follows: ground at G¹⁴, working contact 25 of armature 513 and the said armature, conductor 461, bank contact 446, wiper 442, and armature 418 and its working contact to the conductor 383. It is understood that since 30 the relay 401 is slow acting it does not de- energize until after the ground connection above described has been established.

Before proceeding with the operation of the connector H it will be necessary to return to the incoming selector E and note a number of circuits, which it was not convenient to describe before. When the slow acting relay 402 energizes at the beginning of the vertical movement of the selector, a circuit is completed for the ring cut-off relay 406 35 as follows: ground at G¹⁵, resistance 399, contact springs 337 and 336 of key K⁸, conductor 388, armature 415 and its working contact, and the upper winding of relay 406 to battery. Upon energizing, relay 406 establishes 40 a locking circuit for itself as follows: ground at G¹⁶, off-normal springs 463 and 466, (closed at the first upward movement of the shaft) working contact of armature 428 and the said armature, and the upper winding of the said relay 406 to battery. As a further result of its energization relay 406 disconnects its own lower winding and also a lead extending from the 45 ringing machine IR', and also closes several contacts in the talking circuit. When the off-normal springs 463 and 466 are closed a circuit is completed for the supervisory lamp L⁸ at the attendant operator's position, the circuit being traceable as follows: 50 ground at G¹⁶, off-normal springs 463 and 466, armature 426 and its resting contact, conductor 381, supervisory lamp L⁸, and the armature 310 and its resting contact to battery. The supervisory lamp thus lighted 55 will be extinguished when the connection is completed and the called subscriber answers. It will be advisable also at this time to explain the purpose of the rotary off-normal springs 470 to 472, inclusive. In case all the trunk lines of the selector level are busy, 70 the selector will of course not stop on any of these trunk lines, but will continue to rotate until at the eleventh step a cam on the shaft actuates the rotary off-normal springs, 75 springs 470 and 471 being separated and springs 472 and 473 being closed. At the eleventh step the test wiper 442 will have been rotated past the last test contact in the level, as a result of which operation the relay 403 will not be able to energize again 80 to cause further advance of the switch. Switching relay 404, however, is not energized because of its circuit being open at the rotary off-normal springs 470 and 471. By the engagement of springs 472 and 473 a 85 lead from the busy signaling machine Q' is connected by way of the resistance 469 and the tenth level off-normal springs 460 and 461 to the lower heavy line conductor 389, whereby the toll operator at the distant 90 exchange is given the busy signal. The busy signaling machine Q', preferably produces a tone different in character from the tone used to indicate the busy condition of a called subscriber's line so that the toll operator is able to distinguish between the two. Being informed by the appearance on the line of this distinctive busy test, the operator will know that the connection can not be completed for lack of trunking capacity at 100 the branch exchange and will immediately disconnect. These operations have been mentioned but briefly at this time, but they will be understood fully before the specification is completed. Returning to the connector H, 105 Fig. 6, when the operator dials the next digit of the number, a series of interruptions are produced in the circuit of the line relay 500, being repeated by the relays 100 of the selector W and 201 of the repeater F. Responsive to these interruptions of its circuit the line relay 500 is deenergized a number of times and sends at each deenergization an impulse to the vertical magnet 506 over the following path: ground at G¹⁷, armature 110 512 and its resting contact, armature 514 and its working contact, winding of relay 503, winding of the vertical magnet 506, and the side switch wiper 510 (in first position) to battery. Vertical magnet 506 is accordingly operated to raise the switch shaft step by step until the wipers 540, 541 and 542 arrive opposite the horizontal level in which are located bank contacts which are terminals of the line of substation A. The relay 115 503 is energized in series with the vertical magnet, and being slow acting, retains its armature attracted during the vertical movement of the switch to close a circuit for the private magnet 509. At the end of 120 125 130

the series of impulses the relay 503 and the private magnet deenergize. The latter controls the side switch wipers 510 and 511 in the usual manner and advance them to their 5 second position.

The toll operator may now call the final digit in the number of substation A. As before, a series of interruptions are produced in the circuit of the line relay 500, 10 resulting in another series of deenergizations of the said relay. Now, however, the side switch wiper 510 being in its second position, the line relay 500 transmits a series of impulses to the rotary magnet 507 which 15 is accordingly operated to rotate the wipers 540, 541 and 542 until they come to rest in engagement with bank contacts 543, 544 and 545, respectively. The slow acting relay 503 and the private magnet 509 are energized as before during the last series of impulses, and upon deenergizing, the private magnet advances the side switch wipers 510 and 511 to their third position (it being assumed that the called line is idle). It should 20 be noted that when the private magnet 509 is energized, a circuit is closed for the slow acting relay 504. During the rotation of the switch the two slow acting relays 503 and 504 serve to disconnect the incoming 25 line conductors 460 and 463 from the line wipers 540 and 542, respectively. As soon as the side switch wiper 511 comes into engagement with its third position contact point a circuit is established for the cut-off 30 winding of the line switch C as follows: ground at G¹⁸, side switch wiper 511 in third position, test wiper 541, test contact 544, conductor 547, and the cut-off winding 656 to battery. By the energization of the 35 cut-off winding 656, the cut-off armature 658 is operated to disconnect the line conductors of substations A from their normal battery and ground connections in line switch C. Ground G¹⁸ also extends to multiples of test contact 544 in the banks of the 40 other toll connectors of the group, and likewise to test contact 844 and its multiples in the banks of local connectors, such as the connector H', thereby making the line of 45 substation A busy to other calls.

When the side switch wiper 511 goes to third position, it also closes, in conjunction with the side switch wiper 510, a circuit for the relay 505 which may be traced as follows: ground at G¹⁸, side switch wiper 511 in third position, winding of relay 505, and the side switch wiper 510 in third position to battery. It has been stated before, that the relay 504 is energized during the rotation of the switch, its circuit being closed by the private magnet, and since this relay 504 is slow acting, it remains in operated position for an instant after the relay 505 energizes. During the brief interval that these 50 relays 504 and 505 are both in operated

position the busy signaling machine Q² is connected to the upper line conductor 460, and a circuit is closed for the wiper switching relay 407 of the selector E as follows: ground at G¹⁹, lower winding of relay 407, 70 armature 420 and its working contact, resting contact of armature 431 and the said armature, wiper 440, bank contact 444, conductor 460, armature 517 and its working contact, working contact of armature 518 75 and the said armature, and the secondary winding of the busy signaling machine induction coil, to battery. Upon energizing, relay 407 establishes a locking circuit for itself as follows: ground at G¹⁶, off-normal 80 springs 463 and 466, working contact of armature 432 and the said armature, and the upper winding of the said relay 407 to battery. As a further result of its energization relay 407 connects the line wiper 440 with the condenser 434 and the upper winding of the relay 405 at its armature 431, and at its armature 433 connects the line wiper 443 with the condenser 435, and with the lower winding of the relay 405. The circuits 85 through these armatures 431 and 433 will be traced in detail hereafter.

The toll operator at the main exchange has now completed the required connection, and she will therefore restore her calling device key K³ to its normal position. By this operation the supervisory relay 9 replaces the calling device S in the circuit of the line relay 100 of the selector W, and is energized to again light the supervisory lamp 95 L. The next operation is the signaling of the called subscriber which takes place as follows: When the operator throws her ringing key K⁵, alternating current is projected out over the heavy trunk conductors 100 to the toll second selector W, where it actuates the bridged alternating current relay 111. Upon energizing, the relay 111 closes a circuit for the slow acting relay 104 as follows: ground at G²¹, contact and armature of said relay 111, and the winding of relay 104 to battery. Relay 104 is accordingly energized, and at its upper armature 130 breaks the circuit of relay 203 of the repeater F, thus permitting it to deenergize. 110 At the same time at its lower armature 131, relay 104 closes a circuit for the ringing relay 204 of the repeater F as follows: ground at G²², working contact of armature 131 and the said armature, wiper 152, bank contact 157, conductor 162, and the winding of relay 204, to battery. By the deenergization of relay 203 and the energization of relay 204, a signaling circuit, including the line of substation A, is completed as follows: ground at G²³, generator Gen, working contact of armature 219 and the said armature, resting contact of armature 221 and the said armature, resting contact of armature 217 and the said armature, resting con- 120 125 130

tact of armature 228 and the said armature, working contact of armature 231 and the said armature, trunk conductor 235, contact springs 369 and 368, and contact springs 364 and 365 of key K⁶, contact springs 330 and 331 of key K⁸, contact springs 353 and 354 of key K⁷, conductor 389, working contact of armature 430 and the said armature, condenser 435, left hand working contact of 10 armature 433 and the said armature, wiper 443, bank contact 447, conductor 463, armature 521 and its resting contact, resting contact of armature 516 and the said armature, wiper 542, bank contact 545, normal conductor 15 548, conductor 653, contact springs 672 and 671 of key K¹², contact springs 645 and 644 of key K¹², contact springs 615 and 616 of key K¹¹, line conductor 613, ringer 605, condenser 606, normally closed hook 20 switch contacts, line conductor 612, contact springs 613 and 614 of key K¹¹, resting contact of armature 623 and the said armature, contact springs 641 and 640 of key K¹², contact springs 697 and 649 of key K¹³, conductor 25 650, normal conductor 546, bank contact 543, wiper 540, resting contact of armature 517 and the said armature, conductor 460, bank contact 444, wiper 440, armature 431 and its left hand working contact, condenser 434, conductor 380, contact 30 springs 351 and 352 of key K⁷, contact springs 325 and 326 of key K⁸, contact springs 361 and 360, and contact springs 367 and 366 of key K⁶, trunk conductor 233, 35 armature 230 and its working contact, armature 226 and its resting contact, armature 215 and its resting contact, armature 218 and its working contact, resistance 298, and through the battery to ground G²⁴. The 40 above circuit is closed as long as the toll operator holds her ringing key K⁵ in operated position, and ringing current from the generator Gen operates the ringer 605 at the called substation A to signal the subscriber. It is to be observed that at the selector E, the relay 405 is connected in bridge of the circuit in series, with the battery in readiness to be operated upon the response of the called subscriber. The windings of 45 relay 405 are preferably of rather high resistance, and the relay is given a stiff adjustment so that it does not respond to the ringing current.

When the subscriber at substation A removes his receiver in response to the call, a circuit is closed for the relay 405 at the selector E as follows: ground at G²⁴, lower winding of relay 405, working contact of armature 429 and the said armature, right 50 hand working contact of armature 433 and the said armature, wiper 443, thence over the previously traced circuit to substation A through the transmitter 603, receiver 602, and the upper switch hook contacts at the said substation, and back over the path 55 already traced through the wiper 440, from which point the circuit continues by way of armature 431 and its right hand working contact, armature 427 and its working contact, and the upper winding of relay 405 to 70 battery. The energization of relay 405 responsive of the removal of the receiver has a number of important results. First to be mentioned is the opening of the circuit of the supervisory lamp L⁶ at armature 426, 75 thereby extinguishing the said lamp to notify the attendant operator that the call has been answered. At the same time a circuit is closed for the relay 304 at the attendant operator's position as follows: ground at G¹⁶, off-normal springs 463 and 466, armature 426 and its working contact, conductor 384, contact springs 341 and 340 of key K⁸, and the winding of relay 304 to battery. Upon energizing, relay 304 establishes a locking circuit for itself as follows: ground at G¹⁰, working contact of armature 409 and the said armature, conductor 383, contact springs 317 and 318 of key K¹⁰, armature 311 and its working contact, contact springs 341 and 340 of key K⁸, and the winding of the said relay to battery. At its upper armature 310, relay 304 shifts the circuit of the supervisory lamp L⁶ from its direct battery connection, 85 to battery through the night alarm signal NA for a purpose to be described hereafter. A further result of the energization of relay 405 is the short circuiting of condensers 434 and 435 at armatures 424 and 425, respectively. By this operation a direct metallic connection is established from the toll second selector W through the repeater F, the key circuit equipment M, the incoming selector E, and the connector H to the normal conductors of the called substation A, thereby permitting the battery supply relay 109 at the selector W to be energized over the following path: ground at G⁶, lower winding of relay 109, working contact 90 of armature 116 and the said armature, repeating coil winding 113, wiper 154, bank contact 159, conductor 164, working contact of armature 217 and the said armature, resting contact of armature 228 and the said 95 armature, and the working contact of armature 231 and the said armature to trunk conductor 235, thence through the key circuit equipment M as previously traced, to conductor 389, and thence by way of armature 425 of relay 405 and its working contact, working contact of armature 429 and the said armature, and the right hand working contact of armature 433 and the said 100 armature to wiper 423, from which point the circuit continues to and through substation A and back to wiper 440 over a path previously pointed out, thence by way of armature 431 and its working contact, armature 427 and its working contact, work- 105 110 115 120 125 130

ing contact of armature 424 of relay 405 and the said armature, line conductor 380, thence through the key circuit equipment M as previously traced, to trunk conductor 233, and thence by way of armature 230 and its working contact, armature 226 and its resting contact, armature 215 and its working contact, conductor 160, bank contact 155, wiper 150; repeating coil winding 112, 5 armature 115 and its working contact, and the upper winding of relay 109 to battery.

The energization of relay 109 has the following results: At armature 120 the alternating current relay 111 is disconnected 15 from in bridge of the line conductors; at armature 119 the left hand windings of the repeating coil are connected to complete the talking circuit; at armature 171 ground G²⁵ is connected to the control circuit of 20 the line relay 201 of the repeater F as a substitute for ground G⁶, removed an instant later by the deenergization of line relay 100, as will appear shortly; and at armature 123 conductor 71 is disconnected from 25 the winding of relay 100 and is connected instead to the winding of relay 101. It should be mentioned at this point, that the line relay 100 is of moderate resistance, preferably 250 ohms, while the resistance 30 of the release relay 101 should be at least 1,300 ohms. The supervisory relay at the cord circuit O is marginally adjusted so that it will energize in series with the line relay 100 and deenergize when in series with 35 the release relay 101. It will be seen then that when the relay 109 energizes following the removal of the receiver at the called substation and the resulting energization of relay 405, the resistance of the circuit including 40 the supervisory relay 9 at the cord circuit will be sufficiently increased to cause the deenergization of the said relay. The supervisory lamp L is thus extinguished to notify the toll operator that the called subscriber 45 has answered the telephone.

By the foregoing operations the toll operator has extended the connection to the line of the called subscriber at substation A. The connection to the calling line, presumably 50 connected to the toll line 2-3 at the distant end thereof, is accomplished by inserting the answering plug of the cord circuit O in the jack J, after which the two connected subscribers may converse as desired. The called substation A is supplied 55 with talking current through the winding of relay 405 of the selector E at the branch exchange, and the windings of relay 109 of the selector W at the main exchange in 60 multiple; while the other substation may be supplied with talking current from connective apparatus associated therewith during conversation in any suitable or desired manner. It is to be observed that the connection shown includes but a single induc-

tive connection, the repeating coil at the toll selector W, and with this one exception is direct metallic throughout. There is, moreover, a minimum of bridges across the talking circuit, when all its complexities are 70 considered, resulting in the most efficient transmission possible under the circumstances.

When the conversation is finished the subscribers will replace their receivers. The 75 hanging up of the receiver at substation A brings about the deenergization of relays 405 of the selector E and 109 of the toll selector W. By the deenergization of the former relay, and owing to the fact that the 80 relay 304 at the attendant's switchboard is locked up, the circuit of the supervisory lamp L⁶ is now completed by way of the night alarm signal N_A, and the attendant is thus given both a visual and an audible disconnect signal. At the same time, by the deenergization of the relay 109 at the main exchange the line relay 100 is again inserted in the circuit of the supervisory relay 9 at the cord circuit O, and the latter relay is energized to cause the illumination of the lamp L. The lighting of the supervisory lamp L of course gives the toll operator a disconnect signal. It may happen that the toll operator wishes to talk to the attendant at 95 the private branch exchange concerning the charge for the conversation just finished, or some other matter, in which case she has simply to wait on the line until the attendant responds to the ringing of her night 100 alarm; but ordinarily the toll operator will immediately disconnect the local connection by withdrawing the calling plug of the cord circuit from the jack. Being familiar with these facts, the attendant need not respond 105 except to a prolonged signal.

When the plug is withdrawn from jack J' the circuit of the line relay 100 of the toll selector W is broken. The consequent deenergization of the line relay is followed 110 by the deenergization of the release relay 101, and results also in the breaking of the control circuit including the line relay 201 of the repeater F. By the former operation ground G⁵ is disconnected from the holding 115 circuit extending back to the selector V, and also the line switching relay 110 is permitted to deenergize. At the same time a circuit is closed for the release magnet 106 of the selector W as follows: ground at G⁶, armature 121 and its resting contact, resting contact of armature 118 and the said armature, armature 126 and its resting contact, the off-normal springs 108', and the winding of release magnet 106 to battery. By the energization of the release magnet the selector W is restored to normal position in the usual and well understood manner, the release magnet circuit being opened at the off-normal springs when the shaft reaches its 120 125 130

lowermost position. At the selector V the removal of ground G^s from conductor 17 results in the deenergization of the line switching relay 54 and the extinguishing of the 5 busy lamps at the toll operators' positions. The deenergization of relay 54 results in the closure of the circuit of the release magnet 55 and the selector V is accordingly restored to normal position substantially as 10 was described in the case of selector W.

When the circuit of the line relay 201 of the repeater F is broken and the line relay deenergizes, the release relay 202 deenergizes and also the control circuit extending 15 to the line relay 500 of the connector H at the branch exchange is broken. Following the deenergization of relay 202, the relays of the repeater which were being energized from ground G^7 , and also the cut-off armature of line switch C', are permitted to fall back, and at the same time ground is removed from the test contacts in the banks or the selector switches having access to the repeater.

25 When the line relay 500 of the connector H at the branch exchange deenergizes, it results in the deenergization of the release relay 501 and the breaking of the holding circuit extending back to the selector E via conductor 461. The connector H is restored to normal upon the deenergization of its line and release relays through the medium of release magnet 508. At the selector E, upon the removal of the holding ground supplied from connector H, the line switching relay 404 is deenergized and closes the usual circuit for the release magnet 413, whereupon the selector switch is restored to normal. As the shaft of the selector reaches its lowest position the locking circuits of relays 406 and 407 are broken and these relays deenergize. At the attendant's position the busy lamp L^s is extinguished and the relay 304 is unlocked and deenergized by the removal of ground from conductor 383 which during the connection was joined to conductor 461 extending to the connector H.

It will be seen then that when the toll 50 operator at the main exchange removes the plug from jack J' all the apparatus, including that at the branch exchange is released and restored to normal position. The foregoing description of the releasing operations 55 is rather brief, but there is nothing new or unusual in these operations, and when it is remembered that the various circuits are in general broken in the inverse order to that in which they were established, it is believed 60 that no difficulty will be experienced in understanding them.

It will now be assumed that the subscriber at substation A, when called by the toll operator at the main exchange as described in 65 the foregoing, was engaged in conversation;

and the operations under these circumstances will be briefly described. When the line of substation A is busy there will be a ground potential upon the test contact 544 in the bank of the connector H, and this being the 70 case, when the slow acting relay 503 deenergizes at the end of the final series of operating impulses, the private magnet 509 does not deenergize but is held up over the following test circuit: ground on busy test contact 75 544, wiper 541, side switch wiper 511 in second position, winding of test relay 502, contact 531, spring 532, and the winding of the said private magnet to battery. Since the private magnet is maintained energized the 80 side switch wipers are held in second position, the relay 505 is not energized, and consequently no momentary impulse is transmitted back over conductor 460 to the wiper switching relay 407 of the selector E. The 85 relay 407 therefore does not energize when the connector H lands on a busy line. Instead, at the connector H, the test relay 502 is energized in series with the private magnet and connects the busy signaling machine 90 Q^2 with the lower line conductor 463. Now since the relay 407 at the selector E is not energized the condenser 435 is not included in the lower line circuit and current will flow through the lower winding of relay 109 95 at the toll second selector W at the main exchange over a path which may be briefly traced as follows: ground at G^6 , lower winding of relay 109, working contact of armature 116 and the said armature, repeating 100 coil winding 113, wiper 154, bank contact 159, conductor 164, relay contacts of repeater F, trunk conductor 235, key contacts of key circuit equipment M, conductor 389, working contact of armature 422 and the 105 said armature, resting contact of armature 433 and the said armature, wiper 443, bank contact 447, conductor 463, armature 521 and its working contact, and the low resistance secondary winding of the induction coil 110 of the busy signaling machine Q^2 to battery. By the closure of the above circuit the relay 109 is energized and performs the same functions as in the case where the called subscriber removes his receiver. Among 115 other things, the left hand windings of the repeating coil are connected to enable the operator to hear the busy signal, and also the high resistance relay 101 is substituted for the low resistance relay 100 in the circuit of 120 the supervisory relay 9 at the cord circuit (it being assumed that the operator has restored her calling device key K^3). Upon perceiving the busy signal the operator need not release the connection but may restore 125 her listening key K' and then throw the key K^2 , thus leaving the connection to the busy called line under the control of the supervisory lamp L' . As soon as the line becomes idle the test relay 502 and the private 130

magnet 509 deenergize, the side switch wipers are advanced to third position, and relay 505 is energized to transmit by co-operation with slow acting relay 504 the necessary momentary impulse over conductor 460 to energize relay 407 at the selector E. It should be mentioned here that the private magnet 509 is made slightly slow acting in order to provide a short time interval between the removal of the busy potential from test contact 544 and the reestablishment of this test potential by the advance of side switch wiper 511 to third position, thereby permitting the individual line switch C of substation A to release (assuming that the line was busy as a calling line). When the busy signaling machine Q² is disconnected by the deenergization of the test relay 502, the energizing circuit of relay 109 at the selector W is broken and the relay retracts its armatures. As a result the control circuit including the supervisory relay 9 is again completed by way of the line relay 100 and the relay 9 is accordingly operated to light the lamp L', a red lamp, preferably, whereby the operator is notified that the called line has become idle.

It has been stated before that certain second selectors of the main exchange local trunking system have access to the repeater F by way of the trunk conductors 165, 166, and 167, shown at the upper left hand corner of Fig. 3, whereby local subscribers in the main exchange are enabled to extend connections to subscribers in the branch exchange. I will now briefly describe one of these connections. For this purpose it will be assumed that a calling subscriber in the main exchange has established connection with the bank contacts, 180, 168, and 181, through the medium of automatic switching mechanisms which may consist of an individual line switch and a first and second selector switch. These switches may be similar in most respects to the line switch C and the selector switch E', Fig. 5.

Upon the completion of the connection to the bank contacts named above, the line relay 201 is energized over a circuit which may be traced as follows: ground at G³⁰, lower winding of line relay 201, lower springs of the reversing relay 200, and conductor 165 to bank contact 181, thence by way of the lower selector wiper (not shown), the calling subscriber's loop and the upper selector wiper (also not shown) to the bank contact 180, and thence by way of conductor 167, upper springs of the reversing relay 200, and the upper winding of the line relay 201 to battery. Upon attracting its armature, the line relay 201 completes the usual circuit for the slow acting release relay 202, which is then operated to complete a holding circuit as follows: ground at G⁷, working contact of armature 213 and the said

armature, and conductor 166 to bank contacts 168, whence the circuit extends back to relays in the selector switch and to the holding winding of the individual line switch which are maintained energized in the usual manner to prevent the release of the connection. The other circuits closed at the repeater F following its seizure by the selector and the energization of the line and release relays, including the operating or control circuit extending via conductor 234 to the incoming selector E at the branch exchange, have already been described, the operations being identical with those which take place when the repeater is seized from the toll selector W, with one exception, however, the relay 203, whose circuit can only be completed by way of conductor 161 and a toll second selector such as the selector W, obviously remains deenergized. Such being the case, immediately upon the energization of relay 208 of the repeater, the ringing generator Gen is bridged across the trunk conductors 233 and 235 as follows: conductor 235, armature 231 and its working contact, armature 228 and its resting contact, armature 217 and its resting contact, armature 221 and its resting contact, armature 219 and its resting contact, armature 224 and its resting contact, lamp L¹⁰, contact of the ringing interrupter IR, generator Gen, ground G²³, the grounded exchange battery, the lower winding of the ring cut-off relay 207, resting contact of armature 218 and the said armature, the resting contact of armature 215 and the said armature, the resting contact of armature 226 and the said armature, and the working contact of armature 230 and the said armature to the conductor 233. Since the conductors 233 and 235 are open at the distant end of the trunk, however, and remain open until the connection to the called line is established, no flow of ringing current will take place at present.

The calling subscriber may now proceed to dial the remaining digits in the number, the ones previously called having been effective to control the establishment of the connection as far as the repeater F, and the ones now to be called being those which control the operation of the selector E and the connector H at the branch exchange. Under the control of the line relay 201 of the repeater F the connection is completed precisely as was described in the preceding pages where the toll operator called the substation A. It is to be noted that during the transmission of each series of impulses to the branch exchange, the line relay 201 also sends impulses to the slow acting relay 205, relay 203 being deenergized. The circuit is as follows: ground at G³⁰, armature 212 and its resting contact, armature 214 and its working contact, resting contact of arma-

ture 216 and the said armature, and the winding of relay 205 to battery. Relay 205 is therefore energized during each series of impulses and disconnects the lower trunk conductor 235 from the ringing machine and connects it instead to the lower winding of the busy test relay 206. This operation may be neglected for the present, for it will be assumed that the called line is idle. When 10 the connection is finally completed and the side switch wipers of the connector H are advanced to third position, the wiper switching relay 407 of the selector E is energized in the usual manner to close the line circuit 15 through the selector switch, and the relay 205 at the repeater having by this time de-energized, ringing current from the generator Gen is immediately projected out over the called line. By the operation of the in- 20 interrupter apparatus IR the generator Gen is intermittently cut out of circuit and the booster battery substituted therefor. The ring cut-off relay 207 at the repeater is so adjusted that it will operate on the current 25 from generator Gen and the exchange battery in series when the receiver at the called substation is off the hook, or on current from the exchange battery and the booster battery in series under the same condition; al- 30 though it will not operate from the generator current alone when the receiver at the called substation is hung up.

When the called subscriber responds, therefore, and the relay 405 at the selector E 35 closes the line circuit around the condensers 434 and 435, the relay 207 is energized at once, irrespective of the position of the in- 40 interrupter apparatus IR, and locks itself over the following circuit: ground at G⁷, working contacts of armature 213 and the said armature, and the upper winding of the said relay 207 to battery. A branch of the above 45 circuit supplies ground to the lower winding of the back bridge or reversing relay 200. The lower winding of the relay 200 is connected as shown, rather than to ground direct, in order that the calling subscriber 50 may detect the operation of the ringing apparatus by the tone which he gets by induction between the windings of the relay 207.

To proceed, by attracting its armatures 226 and 228, the ring cut off relay 207 disconnects its lower winding and the lead to the ringing machine, and at the working contacts of these armatures completes the connection from the conductors 167 and 165 to the trunk conductors 233 and 235, respectively, whereupon the talking connection will have been established. In addition to 60 the current which it gets through the windings of the relay 405 of the selector E, the called substation is also supplied with transmitter current through the windings of the relay 200, which is bridged across the talk- 65 ing circuit just to the right of the condensers

at the repeater F. The calling subscriber is of course supplied with talking current through the windings of the line relay 201 of the repeater. When the back bridge relay 200 energizes it reverses the incoming 70 line conductors 167 and 165 as regards their connections to the windings of the line relay 201, thereby reversing the direction of current flow in the calling line. By this means a meter associated with the calling line may 75 be operated, or a coin collected, in the usual and well known manner, to pay for the call.

In the foregoing description of the establishment of the connection from the local main exchange subscriber to the branch ex- 80 change, no attempt has been made to give all the details, it being intended to point out merely wherein the connection differed from the one described before. It is to be understood that the attendant at the branch ex- 85 change has complete supervision over the connection the same as she had in the case of the toll connection.

The release of the connection at the termination of the conversation is brought 90 about by the replacement of the receiver at the calling substation and the consequent de-energization of the line relay 201. This operation does not differ essentially from the releasing operation already described and 95 further explanation thereof will be dispensed with.

The manner in which a main exchange subscriber is given the busy signal when 100 calling a busy line in the branch exchange will now be explained. It will be recollected that in the explanation of the operation of the repeater F in the last described connection, the statement was made that the slow acting relay 205 was energized during each 105 series of impulses to connect the lower trunk conductor 235 with the lower winding of the test relay 206. It has been explained also that when the connector H lands on a busy 110 called line the test relay 502 is energized to connect the lower line conductor 463 with the busy signaling machine Q². Since the relay 205 is slow acting, the test relay 502 will energize before relay 205 has time to de-energize, and a circuit through the lower 115 winding of test relay 206 will be momen- 120 tarily established as follows: ground at G³¹, lower winding of relay 206, working contact of armature 221 and the said armature, resting contact of armature 217 and the said 125 armature, resting contact of armature 228 and the said armature, working contact of armature 231 and the said armature, conductors 235, 389, and 463, armature 521 and its working contact, and the secondary wind- 130 ing of the induction coil of the busy signaling machine Q² to battery. The test relay 206 is energized over the above circuit and locks itself as follows: ground at G⁷, working contacts of armature 213, armature 223

and its working contact, and its upper winding to battery. The energization of the relay 206 has a number of important results. At armature 222 the conductor 237 extending to the cut-off winding of the line switch C' is disconnected from the grounded conductor 166 and is connected instead to the operating or control circuit including conductor 234. At the back contact of armature 223 the circuit of the slow acting relay 208 is broken. When this relay 208 deenergizes an instant later, the trunk conductors 233 and 235 are disconnected from apparatus in the repeater, and at the same time ground 15 G^s is disconnected from the control circuit extending via conductor 234 to the branch exchange, and likewise from the conductor 237 which has just been connected to this circuit. It follows that the apparatus at the 20 branch exchange will all be released and restored to normal and the trunk line cleared for calls from the branch to the main exchange. The reason for connecting the conductor 237 to the operating or control circuit 25 when the test relay 206 energizes will not be gone into now, but will be explained when the branch to main exchange connection is being considered. Finally, at armature 224, relay 206 disconnects the lead extending to the ringing machine, and at armature 225 connects the busy signaling machine Q by way of the lower condenser to the line conductor 165, whereby the calling subscriber is given a busy signal. Being 30 thus informed that the called line is temporarily inaccessible, he will replace his receiver, the line relay 201 of the repeater will be deenergized, and all the equipment not yet released will be restored to normal.

40 A reasonably complete explanation has now been made of the operations whereby either a toll operator or a subscriber at the main exchange can extend a connection to a subscriber at the branch exchange. It 45 may happen, however, that the calling party does not know where the wanted person at the branch exchange is located in which case it will be necessary to call the attendant and ask her to extend the connection.

50 Other circumstances will arise also where it will be desirable to call the attendant rather than the branch exchange subscriber in the first instance. Means must be provided, then, whereby when occasion arises 55 the calling subscriber, or toll operator, can actuate a line signal at the attendant's position at the branch exchange. I will now explain this operation. The general number for calling the branch exchange is the digit 0, which of course is affixed to whatever 60 digits are necessary to be called to obtain connection with the main to branch trunk line. Since but a single digit is called after connection has been extended to this trunk 65 line, it will appear that no connector switch

is operated, and this conclusion is correct. When the incoming selector E responds to the digit 0, a circuit at the attendant's key circuit equipment is prepared for the reception of a signal. I will now explain this 70 feature, particular attention being paid to the key circuit equipment.

It will be assumed that a toll operator, or a subscriber, it is immaterial which, has extended a connection to the trunk line which 75 terminates at the branch exchange in the incoming selector E, and that the line and release relays of the selector have energized to perform their usual functions as already described. Among these, it will be recalled, is the lighting of the busy lamp L¹³ at the attendant's position. Now when the final digit, or the digit 0, is called, the selector E will be operated as before explained to raise its wipers step-by-step until they stand opposite the tenth level, after which the rotary trunk selecting operation is automatically initiated as usual. There are no trunk lines terminating in the tenth level of the incoming selectors and 80 all the test contacts are permanently grounded. The selector E will therefore immediately rotate the full distance, or eleven steps, at which point the test wiper 442 will have been rotated off the bank and 85 the rotation stopped, and the rotary off-normal spring 470-473 shifted to open the circuit of the switching relay 404. The shifting of the rotary off-normal springs does not result in the transmission of a busy 90 signal to the calling party in this instance, however, for when the selector was raised to the tenth level the "tenth level off normal springs," comprising springs 460, 461, and 462, were shifted and such result prevented. Instead, the ringdown and locking relay 303 at the attendant operator's position is bridged across the line circuit as follows: lower line conductor 389, off normal 95 springs 461 and 462, conductor 385, lower winding of relay 303, condenser 397, and resting contact of armature 305 and the said armature to the upper line conductor. When ringing current is projected out over the line, either by the toll operator, or 100 automatically, the relay 303 will respond and will be locked up over the following circuit: grounded conductor 386', armature 311 and its resting contact, armature 308 and its working contact, and the upper 105 winding of relay 303 to battery. By attracting its lower armature 309, relay 303 closes the circuit of the line lamp L⁴ as follows: ground at G³³, armature 309 and its working contact, armature 307 and its resting contact, and the lamp L⁴ to battery.

The illumination of the line lamp L⁴ notifies the attendant that a call has been received, and she will respond by throwing her key K^s to listening position. Her head 110

set will now be bridged across the line circuit, the path through the receiver being traceable as follows: upper line conductor, contact springs 347 and 346 of key K^s , condenser 378, winding 375 of the induction coil, condenser 396, through the receiver by way of the plug connection, conductor 395, and contact springs 339 and 338 of key K^s to the lower line conductor. Another result 5 of the operation of key K^s is the energization of relay 302 over the following circuit: grounded conductor 381, contact springs 345 and 344 of key K^s , relay contacts controlled by armature 306, and the 10 winding of relay 302 to battery. Upon energizing, relay 302 breaks the circuit of the line lamp L^4 at armature 307, and closes a locking circuit for itself as follows: grounded conductor 386', armature 311 and 15 its resting contact, armature 306 and its working contact, and the winding of relay 302 to battery. Still another result of the actuation of key K^s is the closure of a bridge across the line by way of impedance 20 coil 300 to control the supervision at the toll operator's cord circuit by energizing the relay 109 at the toll selector W, or, in case a subscriber is calling, to energize the back bridge relay 200 of the repeater F. 25 This bridge is initially closed by the engagement of contact springs 342 and 343 of key K^s and is maintained intact independent of the key by the engagement of armature 305 of locking relay 302 with its working contact. The attraction of armature 305 also disconnects the bridge including the lower winding of the ring-down relay 303. 30 The attendant may now converse with 35 the calling party and ascertain his wants. In case a connection is desired with a subscriber in the branch exchange the proper procedure for the attendant to pursue is to throw her key K^s to the call in position and dial the required number. First, however, the release in key K^{10} must be operated for a brief interval in order to release the incoming selector E, which it will be recollected has been raised to the tenth level. 40 By the operation of key K^{10} the contact springs 315 and 316 in the operating or control circuit of the selector are separated to break this circuit and restore the selector to normal position. At the same time, by the 45 shifting of spring 318 from spring 317 to spring 319, these springs being preferably arranged to "make before break," conductor 386' is disconnected from conductor 383 and is independently grounded to prevent 50 the deenergization of the locking relays 302 and 303. When the key K^s is thrown to the call in position the line circuit is broken at contact springs 325 and 326, and contact springs 55 330 and 331; and at contact springs 324 and 325, and 331 and 332, the operator's head set is bridged across the section extending ahead. As an additional result, at contact springs 327, 328, and 329, the attendant's calling device is inserted in the 60 control circuit of the selector E, the circuit being as follows: ground at G^{34} , resistance 371, resting contact of armature 372 and the said armature, calling device S', conductor 393, contact springs 329 and 327 of key K^s , 65 contact springs 315 and 316 of key K^{10} , conductor 382, armature 419 and its resting contact, and the winding of line relay 400 to battery. The attendant may now proceed to operate her calling device in accordance with the necessary digits, whereby the selector E and the connector H are operated substantially as before described to establish connection with the called line. There is 70 one essential difference, however, which has 75 to do with the signaling of the called subscriber. When the selector E was operated by the toll operator at the main exchange, it will be remembered that the ring cut-off relay 406 was energized and locked up at 80 the first vertical step of the selector, its initial energizing circuit being closed by the slow acting relay 402. Since this circuit includes the contact springs 336 and 337 of the key K^s , which are now separated, 85 it will be clear that when the attendant at the branch exchange sets up the connection the said ring cut-off relay 406 will not be energized, at least not immediately. It follows that in the present case, when the connection to the called line has been established and the wiper switching relay 407 of the selector has been energized as usual, 90 that signaling current from generator Gen' will be projected over the called line as follows: ground at G^{35} , generator Gen', contact of interrupter IR', the resistance lamp, resting contact of armature 429 and the said armature, right hand working contact of armature 433 and the said armature, wiper 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935

tinguish the supervisory lamp L^6 at the attendant's position, and to close the circuit of the relay 304, all as previously described. Relay 304, upon energizing, locks itself to the grounded conductor 386', transfers the circuit of the supervisory lamp L^6 from direct battery to battery by way of the night alarm, and breaks the locking circuits of relays 302 and 303, thus permitting these relays to deenergize.

The attendant may now converse with the party who has answered the call, and in case the right party has been obtained, will restore her key K^8 to normal, thereby again connecting the calling and called sections of the circuit, and permitting the calling and called parties to engage in conversation. Of course, when the key K^8 is restored the calling device S' is cut out of the control circuit and the connection is left under the control of the calling party, who may be either a toll operator or a subscriber. In fact the connection now is in exactly the same condition as it would be if it had been originally established by either of the above without the intervention of the attendant.

The called subscriber at the branch exchange can recall the attendant at any time by working his receiver hook, thus bringing in the supervisory lamp L^6 and the night alarm. The intermittent sounding of the latter enables the attendant to distinguish it from the ordinary disconnect signal and she will answer at once by throwing her listening key. The listening key is arranged to unlock relay 304 so that in case a different number in the branch exchange is wanted, the new connection may be left under control of the lamp L^6 alone until the subscriber answers, when relay 304 will be again energized to transfer the lamp circuit to the night alarm.

It should be mentioned that when the key K^8 is thrown to the call in position, the exchange battery is connected by way of resistance 392 to one side of the operator's head set. This is done in order to provide a return for the busy signaling current which is applied to the lower line conductor when the connector H lands on a busy line. The resistance 392 is high enough, at least 5000 ohms, so that when the line is idle it will not appreciably interfere with conversation.

In describing all the connections considered until now, it has been assumed that the call through key K^9 at the attendant's position was operated. Such will probably be the usual position of this key, and of course there is no doubt that it would have to be left in operated position, together with similar keys associated with other trunk lines, whenever the attendant was away from the switchboard. But when the attendant is present and not otherwise busy, it is usually

considered to be to the interest of good service to have her intercept all calls and complete the connections herself. This is true because of the fact that she is familiar with the various departments served by the branch exchange and with the duties of the different employees, and is therefore able to distribute the incoming calls to their proper destinations expeditiously and without confusion.

I will now explain the course of a call when the call through key associated with the trunk line over which it is received is in normal position. Assuming that a connection has been extended to the selector E over the trunk line shown, when the calling dial is operated for the next digit and the slow acting relay 402 pulls up in response to the first impulse to the vertical magnet, a circuit will be closed for relay 303 at the attendant's position as follows: ground at G^{10} , working contact of armature 409 and the said armature, armature 414 and its working contact, off-normal springs 467 and 464, winding of the stepping relay 403, conductor 387, contact springs 334 and 333 of key K^8 , contact springs 313 and 314 of key K^9 , contact springs controlled by armature 308 of relay 303, and the upper winding of the said relay to battery. The stepping relay 403 is not energized owing to the high resistance of relay 303 and rotation of the selector E is prevented. The relay 303, however, is energized, locks itself in the usual manner, and closes the circuit of the line lamp L^4 . Upon perceiving the signal, the attendant answers the call as usual; and can complete the connection, after first releasing the selector E through the medium of the release in key K^{10} , by throwing her key K^8 to the call in position and then dialing the required number. It is to be noted that when the key K^8 is actuated the conductor 387 is connected direct to battery by the engagement of contact springs 334 and 335, thereby avoiding the necessity of operating the call through key K^9 . In case a connection had been established while the attendant was away, the call through key K^9 being thrown, if the attendant should now return and take charge of the switch board, the restoration of key K^9 would result in the release of the established connection; for the switching relay 404 of the selector E is energized in series with the stepping relay 403 from battery at the call through key. That is to say, the connection would be released were it not for some provision to guard against this contingency. For this purpose the resistance 450 at the selector E is provided as an alternative path to battery for the circuit of the switching relay, thereby preventing the difficulty above pointed out.

Having described both toll and local connections from the main exchange to the

branch exchange, together with a number of modifications introducing the services of the attendant, I will now explain a few representative connections which may be established in the opposite direction. It will first be assumed that the subscriber at substation A desired to obtain connection with a subscriber in the main exchange. It has been explained before that the line of substation 10 A is a special line and is provided with a special key circuit equipment N at the attendant's position. This equipment is provided largely to enable the attendant to set up connections for the subscriber and relieve 15 him of the trouble of doing so himself, although if he so desires he can put through calls without assistance. We will consider the case where the attendant establishes the connection first. Upon the removal of the 20 receiver at substation A, an energizing circuit is completed by way of the heavy line conductors extending through the key circuit equipment N, for the line relay 654 of the line switch C, this relay being bridged 25 across the conductors 650 and 653 in series with the battery. Upon attracting its armature, the line relay 654 closes a circuit for the pull-in winding 655. Upon energizing, the pull-in winding operates both the plunger arm 657 and the cut-off armature 658; the former, through the medium of its plunger (not shown) forcing the bank springs 30 663-666, inclusive, into engagement, respectively, with contacts 667-670, inclusive; and the latter disconnecting the line conductors 650 and 653, respectively, from the line relay 654 and from ground. By the engagement of bank springs 663 and 666 with contacts 667 and 670, respectively, the 35 line conductors 650 and 653 are extended through normally closed contacts of the switching relay 704 of the selector E' to the double wound line relay 700.

The line relay is accordingly energized 40 over the loop circuit including substation A, and upon attracting its armature, closes a circuit for the slow acting release relay 701. Upon energizing, the release relay 701 prepares the usual circuit for the vertical magnet 45 706, and also closes a holding circuit for the line switch C which may be traced as follows: ground at G³⁷, working contact of armature 709 and the said armature, contact 669, spring 665, and the holding winding 656 to battery. Since the line relay 654 is slow 50 acting, it retains its armature to maintain the pull-in winding 655 energized until after the above holding circuit has been established. A branch of the holding circuit extends 55 by way of conductor 547 to multiple test contacts in the banks of connector switches having access to the line of substation A, where by a ground potential on these test contacts the said line is made busy. 60 A second branch of the holding circuit ex- 65 tends by way of conductor 547 to multiple test contacts in the banks of connector switches having access to the line of substation A, where by a ground potential on these test contacts the said line is made busy. 65

tends by way of conductor 696 to the test contact in the master switch bank which is associated with the trunk line terminating in selector E, whereby the master switch is operated in the usual manner to advance the 70 plungers of all the remaining idle line switches of the group which it controls into position before the terminals of the next idle trunk line.

The engagement of bank spring 664 with 75 contact 668 closes a circuit for relay 621 in the key circuit equipment N as follows: ground at G³⁸, winding of relay 621, conductor 651, bank spring 664, contact 668, conductor 710, normally closed off-normal 80 springs 712 and 713, and the resistance 714 to battery. Upon the closure of the above circuit relay 621 is energized to complete an energizing circuit from ground G³⁸ through the upper winding of relay 620 to battery. 85 Upon energizing, relay 620 establishes a locking circuit for itself at its armature 627 over the following path: ground at G³⁷, working contact of armature 709 and the said armature, contact 669, bank spring 665, 90 conductor 652, armature 627 and its working contact, and the lower winding of relay 620 to battery. By attracting its upper armature 626, the relay 620 closes a circuit for the line lamp L' as follows: ground at G³⁹, 95 working contact of armature 626 and the said armature, armature 628 and its working contact, contact springs 638, 637, 631 and 632 of key K¹², and the lamp L' to battery.

The foregoing operations have occurred 100 in response to the removal of the receiver at substation A. By the illumination of the line lamp L' the attendant is notified that a call has been received and she will immediately answer by throwing the key K¹² to 105 listening position. As a result, the circuit of the line lamp L' is broken at contact springs 631 and 632; and the attendant operator's head set is bridged across the line circuit, the path through the receiver 110 being traceable as follows: upper heavy line conductor, contact springs 634 and 633 of key K¹², conductor 394, condenser 378, winding 375 of induction coil, condenser 396, through the receiver, conductor 395, and 115 contact springs 636 and 635 to the lower heavy line conductor. When the attendant answers, the calling subscriber will tell her what number he wants in the main exchange, and she will then instruct him to 120 hang up his receiver. The key K¹² is now reversed, or thrown to calling position, with the following results: By the separation of contact springs 641 and 644, respectively, from contact springs 640 and 645, the line 125 of substation A is disconnected from the trunk conductors 650 and 653 extending to the individual line switch C; at contact springs 637 and 638 the circuit of the line lamp L' is open at a new point; and at con- 130

tact springs 648 and 649 a circuit is closed for the relay 619 over the following path: ground at G^{40} , contact springs 648 and 649, and the winding of relay 619 to battery. 5 Upon energizing, relay 619 prepares a circuit for the supervisory lamp L^s at its armature 625, bridges the impedance coil 618 across the calling section of the line circuit at armature 623 for a purpose to be described later, and closes a locking circuit for itself as follows: ground at G^{41} , resting contact of armature 622 and the said armature, working contact of armature 624 and the said armature, contact springs 673 and 674 10 of key K^{13} and the winding of relay 619 to battery.

In addition to those above enumerated, the actuation of key K^{12} produces still another result, namely, the closure of a circuit for the relay 370 in the attendant operator's telephone set. This circuit extends as follows: ground at G^{42} , contact springs 639 and 639', conductor 392, and the winding of relay 370 to battery. By the energization of relay 370, in conjunction with the closure of certain contacts of key K^{12} which will be mentioned, the calling device S' is connected in bridge of conductors 650 and 653 as follows: conductor 650, contact springs 649 and 697 of key K^{13} , contact springs 640 and 642 of key K^{12} , conductor 391, working contact of armature 373 and the said armature, calling device S' , armature 374 and its working contact, conductor 390, windings 375, and 377 of this induction coil, conductor 395, contact springs 643 and 645 of key K^{12} , and contact springs 671 and 672 of key K^{13} to conductor 653. The calling device S' is thus substituted for the 20 substation A in the circuit of the line relay 700 of the selector E' .

The attendant will now operate the calling device S' in accordance with the digit 0, the trunk lines to the main exchange being terminated in the tenth level of the local selectors such as the selector E' . By the operation of the calling device a series of ten interruptions is produced in the circuit of line relay 700 which is deenergized 25 a like number of times to transmit ten impulses from ground G^{44} to the slow acting relay 702 and the vertical magnet 706 in series. The vertical magnet is operated responsive to these impulses to raise the switch shaft until the wipers 740, 741, and 742 stand opposite the tenth level. At the first upward movement of the shaft the regular off-normal springs are actuated and the circuit of relay 621 at the attendant's position 30 is broken by the separation of springs 712 and 713, the relay 621 then deenergizing. An instant later ground from G^{45} is supplied to the armature 711 of the relay 702 over the following path: ground G^{45} , contact springs 719 and 720, contact springs 35 715 and 712, and armature 721 and its working contact to armature 711. The relay 702 being energized by this time, the usual initial energizing circuit is completed for the stepping relay 703, which is locked in the usual manner. The contact springs 716 to 720, inclusive, are shifted by the switch shaft when it reaches the tenth level, thus disconnecting ground G^{45} . The armature 711 of relay 702 is still connected to ground, 40 however, by way of conductor 710, the circuit extending as follows: ground at G^{43} , working contact of armature 626 and the said armature, armature 628 and its resting contact, contact springs 676 and 675 of key K^{13} , conductor 651, bank spring 664, contact 668, conductor 710, and armature 721 and its working contact to armature 711. Consequently, when the slow acting relay 702 deenergizes at the end of the series 45 of impulses, a circuit for the rotary magnet 705 will be completed as usual and the switch wipers will be started rotating in search of an idle trunk line. This operation has already been explained several 50 times and need not be gone over again. Assuming that the first idle trunk line encountered is the one shown in the drawing, when the test wiper 741 arrives at bank contact 752, it will find no ground potential 55 and the rotation will cease. The line switching relay 704 is now energized in the usual way to disconnect the incoming line conductors from the windings of the line relay 700 and to extend them instead by way of 60 wipers 740 and 742, conductors 750 and 751, conductors 380 and 389, key circuit equipment M, conductors 233 and 235, and conductors 236 and 238 to the line switch C' at the main exchange. The line relay 244, 65 which is bridged across conductors 236 and 238 in series with the battery, is now energized over the loop circuit extending back to the branch exchange and including the calling device S' at the attendant's position 70 704. Whereupon the line switch C' is operated to establish connection with a trunk line extending to an idle selector switch in the main exchange. Assuming that the trunk selected is the trunk line comprising 75 conductors 241, 242, and 243, the line conductors 236 and 238 will be extended by the operation of the line switch into connection with conductors 241 and 243, respectively; and as a result the line relay of 80 the selector switch in which these latter conductors terminate will be energized. The slow acting release relay of the selector is then energized in the usual manner to place a ground on conductor 242, thereby establishing a holding circuit through the cut-off winding 239 of line switch C' to maintain the switch in operated position. A branch of this holding circuit extends to 85 relay 205 of repeater F as follows: grounded 90

conductor 242, contacts of line switch bank, conductor 237, spring 251, contact 250, conductor 166, armature 213 and its resting contact, and the winding of relay 205 to battery. The conductor 166 being grounded as pointed out above, the repeater F is made busy to the toll and local second selectors in the main exchange. Upon the energization of relay 205, the operating or control circuit of the selector E at the branch exchange is closed as follows: ground at G⁸, armature 229 and its resting contact, armature 220 and its working contact, resistance 209, conductor 234, and thence over the path previously traced to the line relay 400 of selector E. The energization of relay 400 is followed by the energization of the slow acting release relay 401, which establishes a holding circuit extending to the selector E' as follows: ground at G¹⁰, working contact of armature 409 and the said armature, conductor 383, contact springs 317 and 318, conductor 386, bank contact 752, test wiper 741, and the armature 722 and its working contact to junction point 728, where it joins the previously described holding circuit extending back to line switch C, a branch of which also extends through the line switching relay 704 of the selector. The operations involved in the establishment of the holding circuit take place very rapidly and it is completed before the slow acting relay 701 of the selector has had time to deenergize. It will be seen then that when the selector E' seizes the trunk line the line switch C' at the distant end is operated to extend the connection to an idle selector switch, the line and release relays of which are energized to establish a holding circuit for the line switch and to energize a relay in the repeater F. This latter relay has the function of closing the operating circuit of the selector E at the branch exchange, and upon the resulting energization of the line and release relays of this selector a holding circuit is completed for the selector E'. The above operations, although rather complicated, require but few additional circuits, and enable me to do away with a repeater at the branch exchange.

Brief mention should be made of a variation in the operations which take place at the repeater F in case a calling main exchange subscriber who has extended a connection over the conductors 165 and 167 through the repeater F to the branch exchange and is receiving the busy signal. The busy test relay 206 will be in energized position; then when the trunk line extending to the repeater F is seized at this time by a subscriber in the branch exchange the line switch C' plunges in and the operating circuit for selector E will be closed as follows: conductor 237, spring 251, armature

ture 211 and its working contact, resistance 209, conductor 234, and thence to the line relay 400 of the selector E. It will be observed that in this case the operating circuit is closed without the intervention of relay 205. Now if the subscriber who is receiving the busy signal hangs up his receiver before the connection over the trunk is released, the following operations take place: First line relay 201 deenergizes and closes the circuit of slow acting relay 205, which pulls up and closes the operating circuit to ground at G⁸. The release relay 202 now deenergizes and removes ground from conductor 166 to permit the release of the selector switches in the main exchange. At the same time the locking circuit for the test relay 206 is broken, but this relay is slightly slow acting and does not deenergize for an instant, thus allowing a brief interval in which the conductor 166 is clear of ground to permit the main exchange switches to release as mentioned. As soon as relay 206 restores, the grounded conductor 237 is connected to conductor 166, thereby rendering the repeater F busy, and maintaining the relay 205 energized to in turn maintain the operating circuit closed to the selector E.

Having extended the connection to an idle selector switch in the main exchange, the attendant may now operate her calling device S' in accordance with the digits in the telephone number of the main exchange subscriber. A plurality of series of impulses are thus produced in the line circuit extending to the main exchange, in response to which a plurality of automatic switches are operated to complete the connection to the called line. When a response is secured, the attendant will first ascertain that the right party is at the telephone, will ask him to wait a minute, and will then restore her key K¹². By the restoration of the key the attendant's head set is disconnected and the line conductors 612 and 613 of substation A are again connected, respectively, to conductors 650 and 653. Since the subscriber at substation A has replaced his receiver, the connection would be released were it not for the bridge across the line through the impedance coil 618 which was established by the energization of relay 619. Another result of the restoration of key K¹² is the closure of a circuit through the supervisory lamp L⁸ as follows: ground at G⁴⁰, contact springs 648 and 647 of key K¹², armature 625 and its working contact, and the lamp L⁸ to battery. Current flow in the above circuit lights the lamp L⁸. Immediately after restoring her key K¹², the attendant will throw the ringing key K¹¹ to signal the subscriber at substation A. Upon the removal of the receiver a second bridge is closed across the line in addition to the one already established by way of impedance

coil 618. This second bridge extends through substation A and includes the winding of relay 617 at the key circuit equipment N. Relay 617 is accordingly energized, and 5 upon attracting its armature, breaks the locking circuit of relay 619. Relay 619, upon deenergizing, opens the circuit of supervisory lamp L⁸ at armature 625, breaks its own locking circuit at a new point (armature 624), opens the bridge through impedance coil 618 at armature 623, and at the back contact of the same armature 623 short circuits the relay 617.

A complete talking connection has now 15 been established from the line of substation A to the line of the called subscriber in the main exchange which includes no bridges or inductive connections at the branch exchange whatever. The transmitter at substation A 20 is supplied with talking current from the line relay of the connector switch at the main exchange, while the transmitter at the called station is supplied with talking current from the usual back bridge relay of 25 the connector. The connection is entirely under the control of the calling subscriber. When the receiver is replaced at substation A the line relay at the connector in the main exchange is deenergized and the connector and such selector switches as have 30 been used in the connection, including also the line switch C', are released in the usual manner. The operating circuit of selector E in the branch exchange is thereupon 35 broken, following which ground G¹⁰ is removed from the holding circuit of the selector E' and the line switch C to release these switches also.

In case the subscriber at substation A does 40 not answer when the attendant attempts to recall him, the supervisory lamp L⁸ will remain lighted lest the attendant forget the connection, which until the subscriber answers is under her control. If there is no 45 response from substation A in a reasonable time, the attendant may go in on the connection with her listening key and explain matters to the waiting main exchange subscriber. She will then throw key K¹³ to 50 the release position to release the connection. By the operation of key K¹³ the line circuit is broken at contact springs 649 and 697, and 671 and 672, with the above mentioned result; and at contact springs 673, and 674 55 the locking circuit of relay 619 is broken, permitting this relay to deenergize.

Since the substation A is an automatic substation, being provided with the usual calling device, the subscriber can dial a 60 wanted number himself if he so desires. If, in the branch to main connection just described, the subscriber had wanted to call the main exchange subscriber himself, he would have removed his receiver as before; 65 and then, instead of waiting for the attend-

ant to answer, he would have immediately proceeded to dial the number himself. The removal of the receiver of course brings in the line lamp L⁷ at the attendant's position; but the lamp is at once extinguished by the 70 falling back of relay 621 due to the separation of off normal springs 712 and 713 at the first movement of the shaft of selector E'. The lamp is thus put out before the attendant has had time to answer, or possibly before she has even noticed it, from which it follows that the subscriber will be left alone 75 to establish his connection without interference.

A connection to another local subscriber 80 may be completed through the medium of a connector switch such as the connector H', Fig. 6. As before mentioned, the lower levels of the local selectors including the selector E' contain terminals of trunk lines 85 extending to groups of connectors such as the connector H'. It is important to note then that when the selector E' is used in a local connection the shaft will be raised to some level below the tenth and the "tenth 90 level off normal springs," 716 to 720, will not be shifted. There is nothing new in the connector H' and its operation will not be described. It will be necessary, however, to explain more fully than has been done heretofore the function of the above mentioned off normal springs 716 to 720 of the selector E'. The selector switches are each equipped with a set of these springs for the 95 purpose of restricting certain of the branch 100 exchange subscribers to local calls. In the case of special service lines such as the line of substation A calls to the main exchange may be prohibited at will merely by throwing a key in the key circuit equipment N. 105 The utility of this arrangement may be explained as follows: The official in whose office the substation A is located will himself of course have unrestricted service to the main exchange at all times. But when he is 110 absent from his office, leaving a clerk or stenographer in charge, it is desirable to be able to limit such person to local calls, and thus prevent indiscriminate use of the main exchange trunks by employees for private 115 business. Before leaving his office, therefore, the department head or other official served by the substation A will remove his receiver, and when the attendant answers, he will instruct her to stop calls to the main exchange. 120 The attendant will then throw the key K¹³ to the restricted service position, thereby separating the contact springs 675 and 676.

We will assume now that some person attempts to call a subscriber in the main exchange and that the selector E' is selected 125 for use in establishing the connection. When the first digit, or the digit 0, is called, and the switch shaft is raised to the tenth level, the springs 716—720 are actuated and 130

ground G^{45} is disconnected from armature 711 of relay 702, as explained before in the discussion of the branch to main connection. In that case, however, it was assumed that key K^{12} was in normal position, whereby an alternative path to ground existed by way of conductor 710, conductor 651, and the contact springs 675 and 676 of the said key to ground G^{39} . But now the contact springs 675 and 676 are open, and it follows therefore that when the selector E' is raised to the tenth level ground is cut off from armature 711 and the switch is prevented from rotating in search of an idle trunk line. At the same time, by the shifting of spring 717 from spring 716 to spring 718, the lower line conductor is connected to the busy signaling machine Q^8 and the calling party is given a busy signal.

20 The local subscribers' lines which are not equipped as special lines have the bank springs 634 of their individual line switches wired to a terminal where they may be permanently grounded. If it is desired to restrict one of these subscribers to local calls the ground connection associated with his line at this terminal is opened.

There is still another important class of connections which has not yet been described, comprising calls established by the attendant between branch exchange lines not specially equipped and main exchange subscribers. This class of calls will necessarily include all calls from restricted service stations in the branch exchange, and in addition will include calls from subscribers whose outgoing service is not restricted, but who, being themselves very busy, desire to impose the labor of setting up connections upon the attendant.

Since the branch exchange lines now being considered are not provided with the special key circuit equipments such as the equipment N , some arrangement must be provided by which the subscribers on such lines can signal the attendant. The preferable arrangement is to provide a few trunk lines which terminate at one end in a level of the local selectors such as the selector E' and at the other end in a lamp signal and key at the attendant's position, constituting a simple form of the well known information or toll recording trunk. The number of stations at the branch exchange will rarely exceed three or four hundred, and consequently a selector level will ordinarily be available for this purpose. However this may be, some one of many well understood methods will be employed whereby a branch subscriber can signal the attendant, and give her his own number and the number of the wanted main exchange subscriber. The calling branch exchange subscriber will then hang up his receiver, leaving it to the attendant, when she ob-

tains connection with the required party, to call him.

The attendant will now select for use an idle trunk line, which we will assume is the trunk shown in the drawings, and will 70 actuate the hold key K^7 with the following results: By the closure of contact springs 348 and 349 the guard lamp L^5 is lighted. By the shifting of springs 351 and 354 from their respective resting contacts to their 75 working contacts the normally closed short circuiting paths around the condensers 320 and 321 are opened, and the battery supply relay 301 is connected in bridge of the line conductors 380 and 389. Finally, by the 80 closure of contact springs 356 and 357 the impedance coil 300 is connected in bridge of the trunk conductors 233 and 235, resulting in the operation of the line switch C' in the main exchange to select an idle selector 85 switch in the usual manner. The operating or control circuit of selector E is therefore closed as usual through the medium of a relay in the repeater F , and the line and release relays of the selector pull up to 90 render the trunk line busy in the branch exchange. The attendant will now throw her key K^6 to the call out position. This results in the closure at contact springs 358 and 359 of a circuit for relay 370; and the 95 energization of this relay, together with the operation of key contact springs 360 to 365, inclusive, is effective to bring about the substitution of a bridge including the attendant's calling device S' for the bridge through the impedance coil 300. The line relay of the selector switch at the distant main exchange is now energized over a loop which at the branch exchange includes the following: conductor 233, contact springs 366 and 100 367, contact springs 360 and 362, working contact of armature 373 and the said armature, calling device S' , armature 374 and its 105 working contact, windings 375, 376, and 377 of the induction coil, conductor 395, contact 363 and 364, and contact springs 368 and 369 to conductor 235. It follows that 110 when the attendant now operates her calling device in accordance with the digits in the number of the wanted subscriber at the main exchange, a plurality of automatic switches including the selector seized by the line switch C' will be operated to complete the connection in the usual manner. As soon 115 as the called subscriber answers he will be instructed by the attendant to wait a moment, that "someone wishes to speak to him," and the attendant will then restore her key K^6 . After key K^6 is restored the 120 connection is held up by the circuit through the bridged impedance coil 300. The key K^8 is now thrown to the call in position and the attendant dials the number of the local 125 subscriber, the connection being established through the medium of selector E and a toll 130

130

connector such as the connector H. Key K⁸ is then restored also. The supervisory lamp L⁶ is of course lighted when the selector E goes off normal and is extinguished when 5 the branch exchange subscriber answers, thus giving the attendant the usual supervision. The talking connection which has now been established includes the condensers 320 and 321, being separated thereby into 10 two inductively connected sections. Talking current is supplied to the transmitter at the branch exchange substation through the windings of the relay 405 of selector E and relay 301 of the key circuit equipment M in 15 parallel. During the conversation the lamp L⁶ stays out and is lighted when the branch exchange subscriber hangs up, giving the usual disconnect signal. The provision of guard lamp L⁵ is simply an additional pre- 20 caution intended to eliminate any possibility of the attendant neglecting a connection of the above character, for in such a connection neither of the subscribers can release the switches. Lamp L⁵ is preferably a red or 25 green lamp and is obviously lighted continuously while key K⁷ is in operated position.

When the attendant receives the disconnect signal she will restore the hold key K⁷ to normal. When the key is restored the 30 holding bridge through impedance coil 300 is opened, and although the condensers 320 and 321 are short circuited at the same time, nevertheless since there is no other bridge across the line (the branch exchange subscriber having hung up), the connection will 35 be released. If the branch subscriber has removed his receiver again and wants another main exchange member, in which case he will signal the attendant by working his 40 receiver hook, the attendant can release the switches by throwing the key K⁶ to the release out position, thereby opening the line circuit a contact spring 366 to 369, inclusive, and accomplishing the release without 45 waiting for the branch subscriber to hang up again.

All the principal connections which may be established in my improved system have now been described. Variations of these 50 connections, and departures from the operating methods set forth, are possible and are within the purview of the invention; but in consideration of the ample discussion already indulged in are believed to be recognizable by those skilled in the art without further explanation. Before closing, however, it is desired to call particular attention to the method of supplying talking battery to a branch exchange subscriber who 55 has been called over the main exchange trunk line. In every case a certain amount of current is supplied through the windings of the relay 405 of the selector E, but this relay 405 is of rather high resistance, and 60 the principal source of supply is from some

other point. Thus when the branch exchange subscriber is called by a toll operator at the main exchange, a battery supply relay such as the relay 109 of the toll selector W is connected in multiple with the relay 405; when called by a local subscriber in the main exchange the battery supply relay 200 at the repeater F is similarly connected; and when the connection is established by the attendant as in the case last 70 described, the battery supply relay or impedance coil 301 is in service. I rely on these auxiliary sources of supply as the principal source of talking current in order that I may be able, by suitably adjusting 75 the resistances of the different battery supply relays, to regulate the amount of current supplied to meet the requirements of the different connections. Resistance values which have given good results in practice 80 are as follows, the battery potential being 85 46 volts:

Relay 405, each winding, 500 ohms			
" 109, " " 75 ohms			90
" 200, " " 200 ohms			
" 301, " " 250 ohms			

The values given above may of course be varied as circumstances require, and are given merely for the purpose of demonstrating the possibilities of the system.

Having described my invention, what I consider to be new and desire to have protected by Letters Patent will be more specifically pointed out in the appended claims. 100

What I claim as my invention is:

1. In a telephone system, a temporarily established connection including in serial relation a plurality of automatic selector switches, a connector switch, and a called 105 telephone line, and inductive windings in a plurality of said selector switches for supplying talking current to the called line.

2. In a telephone system, a temporarily established connection including in series 110 relation a plurality of automatic selector switches, a connector, and a called telephone line, and a battery supply bridge in each of a plurality of said selector switches, the said bridges being connected in multiple to supply talking current to the called line.

3. In a telephone system, a temporarily established connection including in serial relation the calling line, a trunk line, a repeater, a pair of automatic progressively 120 movable switches, and the called telephone line, a battery supply relay bridged across the line at the first automatic switch in the series, and a second battery supply relay bridged across the line at the repeater, the 125 said relays in parallel feeding talking current to the called line.

4. In a telephone system, a temporarily established connection including in serial relation, a trunk line, a repeater, a selector 130

- switch, a connector switch, and a called telephone line, and multiply connected relays in the selector switch and in the repeater for feeding talking current to the called line.
5. In a telephone system, a temporarily established connection including in serial relation, a trunk line, a repeater, a selector switch, a connector switch, and a called telephone line, a relay bridged across the called line at the repeater in series with a battery, normally open contacts in the talking conductors at the selector, and a relay responsive to the removal of the receiver on the called line for closing said contacts.
10. In a telephone system, a temporarily established connection including in serial relation, a trunk line, a repeater, a selector switch, a connector switch, and a called telephone line, a relay in series with a battery bridged across the called line at the selector for controlling the continuity of the talking circuit, and a second relay and battery bridged across the line at the repeater for increasing the supply of talking current to the called line.
15. In a telephone system, a temporarily established connection including in serial relation, a trunk line, a repeater, a selector switch, a connector switch, and a called telephone line, and inductive windings at the selector and at the repeater connected in multiple across the line in series with a battery for supplying talking current to the called line.
20. In a telephone system, a trunk line, two different kinds of automatic switches having access to said trunk, means for extending said trunk line when seized by a switch of either kind into connection with a called telephone line, two battery supply bridges associated with said trunk for supplying talking current to the called line, and means whereby if the said trunk is seized by a switch of a particular kind a third battery supply bridge is substituted for one of said first bridges.
25. In a telephone system, a trunk line, automatic switches of different kind having access to said trunk, means for extending said trunk line when seized by a switch of either kind into connection with a called telephone line, a battery supply bridge connected across said trunk to supply talking current to the called line, excess battery supply bridges having different resistances, means for connecting up one of said last bridges when the connection is established via one kind of switch, and means for connecting up the other of said last bridges when the connection is established via the other kind of switch.
30. In a telephone system, a trunk line, means including an automatic switch for extending a connection to said line from two different points, a battery supply bridge in said switch for supplying talk-
- ing current to the connected called line, an excess battery supply bridge connected in multiple with said first bridge when the connection is extended from one point, and a second excess battery supply bridge similarly connected when the connection is extended from the other point, the said excess battery supply bridges being of different resistances.
35. In a telephone system, an operator's position, a called telephone line, means for automatically extending a connection from the said operator's position to the called line, said means comprising in serial relation a selector switch, a repeater, another selector switch and a final connector, and continuous metallic talking circuit conductors extending from the first of said selector switches to the substation on the called line.
40. In a telephone system, a first operator's position, a second operator's position, a called telephone line, means for automatically extending a connection from the said first operator's position to the called line, said means comprising in serial relation a selector switch, a repeater, a trunk line extending through the second operator's position and a final connector switch, and continuous metallic talking circuit conductors extending from the selector switch to the substation on the called line.
45. In a telephone system, an operator's position, a called telephone line, connecting means comprising in serial relation first and second selector switches, a repeater, a third selector and a connector switch for extending a connection from the operator's position to the called line, a repeating coil at the second selector, and continuous metallic talking conductors extending from the repeating coil to the substation on the called line.
50. In a telephone system, a first operator's position, a second operator's position, a called telephone line, automatic connecting means for extending a connection from the said first operator's position to the called line, said means comprising in serial relation a selector switch, a repeater, a trunk line extending through the second operator's position, another selector switch, and a final connector, a repeating coil at the first of said selector switches, and continuous metallic talking conductors extending from said repeating coil to the substation on the called line.
55. In a telephone system, a first operator's position, a second operator's position, a called telephone line, automatic connecting means for extending a connection from the said first operator's position to the called line, said means comprising in serial relation a selector switch, a repeater, a trunk line extending through the second operator's position, and a final connector, a repeating coil at the first of said selector switches, and continuous metallic talking conductors extending from said repeating coil to the substation on the called line.
60. In a telephone system, a first operator's position, a second operator's position, a called telephone line, automatic connecting means for extending a connection from the said first operator's position to the called line, said means comprising in serial relation a selector switch, a repeater, a trunk line extending through the second operator's position, and a final connector, a repeating coil at the first of said selector switches, and continuous metallic talking conductors extending from said repeating coil to the substation on the called line.
65. In a telephone system, a first operator's position, a second operator's position, a called telephone line, automatic connecting means for extending a connection from the said first operator's position to the called line, said means comprising in serial relation a selector switch, a repeater, a trunk line extending through the second operator's position, and a final connector, a repeating coil at the first of said selector switches, and continuous metallic talking conductors extending from said repeating coil to the substation on the called line.

continuous metallic talking conductors extending from said repeating coil to the substation on the called line.

16. In a telephone system, an operator's position, a called telephone line, means for automatically extending a connection from the said operator's position to the called line, said means comprising in serial relation a selector switch, a repeater, another selector switch and a final connector, continuous metallic talking circuit conductors extending from the first of said selector switches to the substation on the called line, and serially related conductors separate from the talking circuit for controlling the operation and release of the said switches.

17. In a telephone system, a first operator's position, a second operator's position, a called telephone line, means for automatically extending a connection from the said first operator's position to the called line, said means comprising in serial relation a selector switch, a trunk line extending through the second operator's position and a final connector switch, continuous metallic talking circuit conductors extending from the selector switch to the substation on the called line, and serially related conductors separate from the talking circuit for controlling the operation and release of the said switches.

18. In a telephone system, an operator's position, a called telephone line, connecting means comprising in serial relation first, second, and third selectors and a connector switch for extending a connection from the operator's position to the called line, a repeating coil at the second selector, continuous metallic talking conductors extending from the repeating coil to the substation on the called line, and serially related conductors separate from the talking circuit for controlling the operation and release of the said switches.

19. In a telephone system, an operator's position, a called telephone line, connecting means comprising in serial relation first and second selector switches, a repeater, a third selector and a connector switch for extending a connection from the operator's position to the called line, a repeating coil at the second selector, continuous metallic talking conductors extending from the repeating coil to the substation on the called line, and serially related conductors separate from the talking circuit for controlling the operation and release of the said switches.

20. In a telephone system, a first operator's position, a second operator's position, a called telephone line, means for automatically extending a connection from the said first operator's position to the called line, said means comprising in serial relation a selector switch, a repeater, a trunk line ex-

tending through the second operator's position and a final connector switch, continuous metallic talking circuit conductors extending from the selector switch to the substation on the called line, and supervisory signals at both operators' positions controlled by the called subscriber.

21. In a telephone system, a first operator's position, a second operator's position, a called telephone line, automatic connecting means for extending a connection from the said first operator's position to the called line, said means comprising in serial relation a selector switch, a repeater, a trunk line extending through the second operator's position, another selector switch, and a final connector, a repeating coil at the first of said selector switches, continuous metallic talking conductors extending from said repeating coil to the substation on the called line, and supervisory signals at both operators' positions controlled by the called subscriber.

22. In a telephone system, means including a repeater and an automatic switch controllable thereby for connecting a calling and a called line, and two different kinds of ringing equipment in said repeater for signaling the called line, the ringing equipment of one kind being automatic and the other kind being manually controlled.

23. In a telephone system, means including a repeater and an automatic connector switch for completing connections to called subscribers' lines, said repeater accessible to calling subscribers and to operators in common, means in said repeater for performing automatic or operator controlled signaling operations on a called line, and discriminating means dependent on whether said repeater is being used by a calling subscriber or by an operator for determining the character of the signaling operation.

24. In a telephone system, means including an automatic impulse repeater and a connector switch for completing connection to a called line, trunk lines of two kinds and associated automatic switches for connecting the several trunk lines with said repeater separately, means for operating said connector over a connected trunk line through the medium of said repeater, a busy test relay in said repeater responsive to the busy condition of the called line, and discriminating means whereby the said relay performs its function only when connection has been extended to said repeater via a trunk line of a particular kind.

25. In a telephone system, a two way trunk line, a plurality of automatic switches for extending a connection from a calling line to said trunk line, a second plurality of switches for extending the said trunk line to a called line, and automatic means responsive to the busy condition of the called

line for releasing the switches of said second plurality without releasing those of the first, for clearing the said trunk line to calls in the other direction, and for giving 5 the calling subscriber a busy signal.

26. In a telephone system, a repeater, automatic switching mechanisms for extending a connection from a calling line to said repeater, other automatic switching mechanisms controllable through the medium of the repeater for further extending the connection to a called line, means responsive to the busy condition of the called line for releasing the connection between the repeater 10 and the called line, and means in the repeater for giving the calling subscriber a busy signal.

27. In a telephone system, a calling line, means including a repeater and a plurality 20 of automatic switches controllable thereby for extending a connection from said line to a called line, and a test relay in said repeater responsive to the busy condition of the called line for giving the calling subscriber a busy signal.

28. In a telephone system, a calling line, means including a repeater and a plurality of automatic switches controllable thereby for extending a connection from said line to a called line, a test relay in said repeater responsive to the busy condition of the called line for giving the calling subscriber a busy signal, and means controlled by said relay for releasing said switches.

35. 29. In a telephone system, a two way trunk line terminating at each end in an automatic switch, a third conductor, means for controlling the operation of the switch at one end over the two line conductors of 40 the trunk in series, and means for controlling the operation of the switch at the other end over said third conductor.

30. In a telephone system, a two way trunk line terminating at each end in an automatic switch, other automatic switches at 45 each end adapted to establish connection with said trunk line, the connection at one end being made by way of a repeater, and means in said repeater for making the said 50 trunk line busy at both ends whenever the same is seized by an automatic switch at either end.

31. In a telephone system, a two way trunk line terminating at each end in an automatic switch, other automatic switches at 55 each end adapted to establish connection with said trunk line, means responsive to the seizure of said trunk line at either end for completing a control circuit for the associated switch at the other end, and means responsive to the closure of one of said control circuits for closing the other.

32. In a telephone system, a two way trunk line terminating at each end in an 60 automatic switch, other automatic switches

at each end adapted to establish connection with said trunk line, means responsive to the seizure of said trunk line at either end for completing a control circuit for the associated automatic switch at the other end, 70 means responsive to the closure of one of said control circuits for closing the other, and means for transmitting operating impulses over the control circuit first established while maintaining the other circuit 75 closed.

33. In a telephone system, a two way trunk line terminating at each end in an automatic switch, other automatic switches at each end adapted to establish connection with 80 said trunk line, means responsive to the seizure of said trunk line at either end for completing a control circuit for the associated automatic switch at the other end, means responsive to the closure of one of said control 85 circuits for closing the other, and means responsive to the closure of the circuit last closed for rendering the said trunk line busy at the seized end thereof.

34. In a telephone system, a central exchange, a trunk line terminating in an automatic switch for distributing calls to said exchange, a plurality of other automatic switches having access to said trunk line for transmitting calls from said exchange, and 90 means responsive to the seizure of said trunk line by one of said other switches for energizing a relay in said first switch to 95 close a circuit whereby the said trunk line is rendered inaccessible to the remaining 100 switches of said plurality.

35. In a telephone system, a central exchange, a trunk line terminating in an automatic switch for distributing calls to said exchange, a plurality of other automatic 105 switches having access to said trunk line for transmitting calls from said exchange, and means responsive to the seizure of said trunk line by one of said other switches for energizing a relay in said first switch to close 110 a holding circuit to prevent the release of the switch by which the trunk line was seized.

36. In a telephone system, a trunk line extending in two directions from an operator's position, a key at the operator's position operable to divide said trunk line into two inductively connected sections, and automatic switches controllable by the operator for extending each section into connection with a subscriber's telephone line, whereby two subscribers' lines may be connected.

37. In a telephone system, a trunk line extending in two directions from an operator's position, a key at the operator's position operable to divide said trunk line into two inductively connected sections, automatic switches controllable by the operator for extending each section into connection 120 125 130

with a subscriber's telephone line, whereby two subscribers' lines may be connected, and means at the operator's position for supervising the connection.

- 5 38. In a telephone system, a trunk line extending in two directions from an operator's position, a key at the operator's position operable to divide said trunk line into two inductively connected sections, automatic switches controllable by the operator for extending each section into connection with a subscriber's telephone line, whereby two subscribers' lines may be connected, and means responsive to the restoration of said 10 key to release the connection at both ends when disconnection is desired.

39. In a telephone system, a trunk line extending in two directions from an operator's position and terminating at each end in an automatic switch, means whereby a calling subscriber may extend a connection over said trunk line to a called line, a device at the operator's position operable to divide said trunk line into two inductively connected sections, and means whereby the operator can extend the said sections, respectively, into connection with a calling and a called line to establish a connection between them.

40. In a telephone system, a trunk line extending in two directions from an operator's position and terminating in each end in an automatic switch, means whereby a calling subscriber may extend a connection 35 over said trunk line to a called line, a device at the operator's position operable to divide said trunk line into two inductively connected sections, means whereby the operator can extend the said sections, respectively, 40 into connection with a calling and a called line to establish a connection between them, and means for releasing the connection at both ends when the said device is restored to normal.

41. In a telephone system, a trunk line extending through an operator's position and terminating in an automatic switch, other trunk lines accessible to said switch, means for operating said switch in accordance with a digit in a called number to select an idle trunk line, means for transmitting signaling current over the two connected trunk lines, and a signaling device at the operator's position connected to receive said signaling current if the said switch is operated in accordance with a particular digit.

42. In a telephone system, an operator's position, a trunk line extending through 60 said position and terminating in an automatic trunking switch, automatic means for seizing said trunk line and for transmitting operating impulses thereover to control said switch, a line signal at the operator's position, and a circuit for actuating said

signal closed only by the operation of said switch in response to a particular number of impulses.

43. In a telephone system, an operator's position, a trunk line extending through 70 said position and terminating in an automatic trunking switch, automatic means for seizing said trunk line and for transmitting operating impulses thereover to control said switch, and a signal controlling relay connected in bridge of the trunk line conductors when said switch is operated in response to a particular number of impulses.

44. In a telephone system, an operator's position, an automatic trunking switch, a 80 trunk line accessible to said switch and extending through said position to a second automatic switch, means including said switches and trunk line whereby a calling subscriber may extend a connection to a 85 called line, and a busy signal at the operator's position operated whenever the trunk line is in use.

45. In a telephone system, an operator's position, an automatic trunking switch, a 90 trunk line accessible to said switch and extending through said position to a second automatic switch, means including said switches and trunk line whereby a calling subscriber may extend a connection to a 95 called line, and a supervisory signal at the operator's position operated by said second switch and under control of the subscriber on the called line.

46. In a telephone system, an operator's 100 position, an automatic trunking switch, a trunk line accessible to said switch and extending through said position to a second automatic switch, means including said switches and trunk line whereby a calling 105 subscriber may extend a connection to a called line, a signal at the operator's position to indicate the busy condition of the trunk line, and means whereby the operator may listen in without interfering with the 110 establishment of the connection.

47. In a telephone system, an operator's position, an automatic trunking switch, a trunk line accessible to said switch and extending through said position to a second 115 automatic switch, means including said switches and trunk line whereby a calling subscriber may extend a connection to a called line, a supervisory signal at the operator's position extinguished when the 120 called subscriber answers, and an audible signal automatically connected at the same time, whereby when the called subscriber hangs up the operator will be given both a visual and an audible disconnect signal. 125

48. In a telephone system, a trunk line extending through an operator's position and terminating in an automatic trunking switch, a second operator's position, means including said trunk line and switch where- 130

by the operator at the said second position may extend a connection to a called line, and a busy signal at the said first position operated whenever the trunk line is in use.

5 49. In a telephone system, a trunk line extending through an operator's position and terminating in an automatic trunking switch, automatic means including said trunk line and switch whereby a calling subscriber may extend a connection to a called line, means at the operator's position for rendering said switch inoperative, and a signal for indicating when said subscriber attempts to make a call after the selector has been rendered inoperative to him.

10 50. In a telephone system, an operator's position, means including a plurality of automatic switches for extending a connection to a called telephone line, condensers included in the established connection, a relay in series with a battery bridged across the connection on the operator's side of the said condensers, and another relay 25 actuated on the response of the called subscriber for short-circuiting said condensers whereby the said first relay may be energized over the called line, the entire supply of talking current to the called line being 30 supplied through both of said relays in parallel.

35 51. In a telephone system, an automatic switch provided with automatic ringing equipment, means whereby either an operator or a calling subscriber may utilize said switch in extending a connection to a called line, means whereby when said switch is in use by a calling subscriber the said ringing equipment is automatically disconnected and other equipment substituted 40 therefor, and means whereby when said switch is in use by the operator such disconnection is prevented.

45 52. In a telephone system, means including a selector switch and a final connector for extending connections to called lines, normally open contacts in the talking conductors at the selector, and a relay automatically controlled by the connector when 50 it connects with an idle called line for closing said contacts.

55 53. In a telephone system, means including a selector switch and a final connector for extending connections to called lines, normally open contacts in the talking conductors at the selector, a relay automatically controlled by the connector when it connects with an idle called line for closing said contacts, and a circuit over which the control is exercised including a talking conductor extending between the selector and connector.

60 54. In an automatic telephone exchange system, two kinds of subscribers' lines comprising standard automatic lines and spe-

cial service lines, automatic switching mechanisms at the exchange adapted for use by the subscribers on both kinds of lines for extending connections to called lines, an operator's position, and a special equipment thereat associated with each special service line whereby if the subscribers on such lines so desire the operator may control the automatic switching mechanisms to set up the connections for them. 75

55. In a telephone system, a subscriber's line extending through an operator's position and terminating in an automatic trunking switch, a line signal at the operator's position automatically actuated when the subscriber removes his receiver, and a plurality of other switches controllable either by the subscriber or by the operator to connect the said line with another line. 80

56. In a telephone system, a subscriber's line extending through an operator's position and terminating in an automatic trunking switch, a line signal at the operator's position actuated when the subscriber removes his receiver, a plurality of other switches 90 controllable either by the subscriber or by the operator to connect the said line with another line, and means whereby if the connection is established by the subscriber the said signal will be extinguished upon the 95 operation of one of said switches.

57. In a telephone system, a subscriber's line extending through an operator's position and terminating in an automatic trunking switch, a line signal at the operator's position actuated when the subscriber removes his receiver, a plurality of other switches controllable either by the subscriber or by the operator to connect the said line with another line, means whereby 100 if the subscriber replaces his receiver while the operator is establishing the connection it may be maintained independent of the operator when established, means for recalling the subscriber, and automatic means responsive when the receiver is again removed to place the connection under the control of the subscriber. 105

58. In a telephone system, an automatic subscriber's station and a line therefor extending to an exchange and terminating in an automatic switch directly controllable by the subscriber for extending connection to a called line, an operator's position, and a line signal thereat actuated when the subscriber removes his receiver and a calling device at the operator's position for operating said automatic switch to extend a connection, from the subscriber's station. 115

59. In a telephone system, an automatic subscriber's station and a line therefor extending to an exchange and terminating in an automatic switch directly controllable by the subscriber for extending connection to a called line, an operator's position, a line 120 125

signal thereat actuated when the subscriber removes his receiver, means for extinguishing said signal when said switch is operated, and a calling device at the operator's position for operating said switch to extend the connection from the subscriber's line.

60. In a telephone system, an automatic subscriber's station and a line therefor extending to an exchange and terminating in an automatic switch directly controllable by the subscriber for extending connection to a called line, an operator's position, a line signal thereat automatically actuated when the subscriber removes his receiver, and means whereby if the subscriber so desires the connection to the called line may be extended by the operator.

61. In a telephone system, an automatic subscriber's station and a line therefor extending to an exchange and terminating in an automatic switch directly controllable by the subscriber for extending connection to a called line, an operator's position, a line signal thereat actuated when the subscriber removes his receiver, means whereby if the subscriber so desires the connection to the called line may be extended by the operator, and a supervisory signal controlled by the called subscriber.

62. In a telephone system, subscribers' lines terminating in a central exchange, a second exchange, automatic switching mechanisms controllable by the subscribers on said lines for completing local or interexchange connections, a supervising operator's position, and means whereby the operator may at her option restrict the subscribers to local connections.

63. In a telephone system, a subscriber's line, an automatic switch at the exchange controllable by the subscriber for extending connections, local trunk lines and trunk lines extending to another exchange accessible to said switch, and means controlled by an operator for preventing the subscriber from operating said switch to connect with the trunk lines extending to the other exchange.

64. In a telephone system, a subscriber's line, an automatic switch at the exchange controllable by the subscriber for extending connections, local trunk lines and trunk lines extending to another exchange accessible to said switch, an operator's position, and a key thereat effective when actuated to restrict the subscriber to connections extended via said local trunk lines.

65. In a telephone system, a trunk line extending through an operator's position and terminating in an automatic trunking switch, automatic means including said trunk line and switch whereby a calling subscriber may extend a connection to a called line, a device at the operator's position for rendering said switch inoperative,

and a signal for indicating when said subscriber attempts to make a call after the selector has been rendered inoperative to him.

66. In a telephone system, a trunk line extending to a branch exchange and terminating in an automatic switch, means including said trunk line and switch whereby calling main exchange subscribers can normally extend connections to called lines in the branch exchange, multiple terminals of said trunk line at an operator's position, and means put in use at the option of the operator for switching all calls to her position and for preventing their extension to called lines by the calling subscribers.

67. In a telephone system, a trunk line extending to a branch exchange and terminating in an automatic switch, means including said trunk line and switch whereby calling main exchange subscribers can normally extend connections to called lines in the branch exchange, multiple terminals of said trunk line at an operator's position, means whereby the operator can delay or stop all calls at her position if she so desires, and means for completing such delayed calls under operator control.

68. In a telephone system, a trunk line extending through an operator's position and terminating in an automatic trunking switch, automatic means including said trunk line and switch whereby a calling subscriber can extend connections to called lines, means whereby the operator may at her option prohibit such extension of calls, and a line signal at the operator's position automatically actuated whenever a prohibited connection is attempted.

69. In a telephone system, a trunk line extending through an operator's position and terminating in an automatic trunking switch, a second operator's position and means whereby connections can be extended to called lines therefrom through the medium of said trunk line and switch, means at said first position adapted to be set to block all calls attempted to be so extended, and a line signal automatically actuated whenever a call is blocked.

70. In a telephone system, a trunk line extending through an operator's position and terminating in an automatic trunking switch, automatic means including said trunk line and switch whereby a calling subscriber may extend a connection to a called line, and means at the operator's position for blocking calls attempted to be so extended and for preventing the extension of such calls beyond said position.

71. In a telephone system, a trunk line extending through an operator's position and terminating in an automatic trunking switch, automatic means including said trunk line and switch whereby a calling

subscriber can extend a connection to a called line, a source of operating current for said switch, and means whereby the operator at said position can disconnect said source from said switch to prevent the extension of calls thereby.

72. In a telephone system, a main to branch exchange trunk line extending through an operator's position and terminating in an automatic switch, means for operating said switch in completing main to branch exchange connections, a battery normally connected to said switch to supply current for operating the same, and means under the control of the operator at said position for disconnecting said battery.

73. In a telephone system, a main to branch exchange trunk line extending through an operator's position and terminating in an automatic switch, means for operating said switch in completing main to branch exchange connections, a battery normally connected to said switch to supply current for operating the same, and a key at said operator's position for disconnecting said battery.

74. In a telephone system, a trunk line extending in two directions from an operator's position and comprising incoming and outgoing sections, normally connected, automatic switches for connecting each section with a subscriber's telephone line to establish a connection between two lines, and means for disconnecting said sections temporarily to prevent interference while the switches are being operated.

75. In a telephone system, a trunk line extending in two directions from an operator's position, means for dividing said trunk line into two sections connected by condensers, automatic switches controllable by an operator for extending each section into connection with a subscriber's telephone line, an open connection in one of said sections for preventing interference while said switches are being operated, and operator controlled means for closing said open connection to complete a talking connection between said telephone lines.

76. In a telephone system, a main to branch exchange trunk line extending through an operator's position and terminating in an automatic switch, means for dividing said trunk at said position into two

sections, an incoming section and an outgoing section, means whereby a calling main exchange subscriber can connect with the incoming section, operator controlled means including said switch for extending the outgoing section to a called line in the branch exchange, and operator controlled means for connecting said sections.

77. In an automatic telephone system, a branch exchange having an attendant operator's position, a trunk line incoming to said branch exchange from a main exchange and accessible at the distant end to main exchange subscribers, automatic switching devices at the branch exchange controllable either by the attendant operator or by calling main exchange subscribers for extending said trunk line to called lines in the branch exchange, and a trunk busy signal at the attendant's position operated whenever the trunk line is in use.

78. In an automatic telephone system, a branch exchange having an attendant operator's position, a trunk line incoming to said branch exchange from a main exchange and accessible at the distant end to main exchange subscribers, automatic switching devices at the branch exchange controllable either by the attendant operator or by calling main exchange subscribers for extending said trunk line to called lines in the branch exchange, and a trunk supervisory signal at the attendant's position controlled by connected called subscribers.

79. In an automatic telephone system, a trunk line connecting a main and a branch exchange and extending through an operator's position at the branch exchange, switches at each exchange accessible to the subscribers therein and operable to connect with said trunk, a terminal switch at each end of the trunk controllable thereover by a calling subscriber when the trunk is connected with at the other end, a signal at the operator's position actuated when the trunk line is being used by a subscriber in either exchange, and means whereby the operator can control either of said terminal switches to extend a connection when the trunk line is not otherwise in use.

Signed by me at Chicago, Cook county, 105 State of Illinois, this 31st day of March, 1917.

WINFRED T. POWELL.
